UNITED STATES PATENT OFFICE.

JOSEPH A. V. TURCK, OF CHICAGO, ILLINOIS, ASSIGNOR TO FELT & TARRANT MANUFACTURING COMPANY, A CORPORATION OF ILLINOIS.

CALCULATING-MACHINE.

1,316,523.

Specification of Letters Patent. Patented Sept. 16, 1919.

Application filed August 21, 1914. Serial No. 857,869.

To all whom it may concern:

Be it known that I, JOSEPH A. V. TURCK, a citizen of the United States, residing at Chicago, in the county of Cook and State of Illinois, have invented a new and useful Improvement in Calculating-Machines, of which the following is a specification.

My invention relates to multiple order keyboard calculating machines, and has for its general objects to perform automatically the process of multiplication and other calculations involving any suitable character of multiple strokes or actuations of an adding mechanism and repetitions of the same number, taken either positively or negatively, by a purely mechanical operation according to the denominations of the multiplicand and multiplier, or according to other elements of the problem, without the necessity of progressive and separate settings of the parts during the performance of the operation; also to enable addition and subtraction to be performed on the same machine without interference from the multiplying mechanism; also to convert the machine from key driven to key set, and vice versa, for all purposes for which such conversion is or may be desirable. By preference the well known comptometer, set forth in the Felt Patent 960,528, dated June 7, 1910, and in other patents embodied in the present commercial comptometer, is used for the purpose of addition and subtraction, and it is a further object of the invention to combine with such comptometer automatic multiplying or multiple stroke mechanism in such manner that the said mechanism may be operatively connected with the accumulator mechanism of the comptometer irrespective of the keys of the latter, or disconnected therefrom without removing the multiplying mechanism. In the former condition the accumulator mechanism of the comptometer is used for automatic multiplication and other multiple stroke calculation; in the latter condition the multiple stroke mechanism is idle and does not interfere with the free use of the comptometer in the usual manner. The invention has for further objects to perform automatically many operations subsidiary to the aforesaid general objects, and which will be best under-

stood from the following description. And the invention has for further objects the effecting of all other improvements in structure or function that may be found to obtain in the mechanism hereinafter described or claimed.

An object of this invention is to provide automatic means to accomplish multiplication and division, which may be applied to the comptometer, or other suitable adding machine, without affecting its present efficiency in its use as a rapid key-driven multiple order calculating machine with a capacity of simultaneous key action of all the orders.

While heretofore it has been possible to multiply with considerable speed on the comptometer it has required a considerable amount of instruction to teach an operator to become proficient in multiplication; again in shifting from one set of keys to another in the operation there was a chance for making an error. In some cases keys to be struck come in such order that it is almost impossible to reach them with the utmost exertion of the operator. In multiplication it is absolutely necessary that the operator should give the keys the exact number of strokes to each number to be multiplied. This requires considerable practice, owing to the confusion arising from the noise caused by the mechanism, which breaks the rhythm of count until the operator becomes accustomed to it. In long division where the divisor has more than six places, the operation is much more complicated and confusing to the beginner. It is obvious, therefore, that the mere setting up of the multiplier and multiplicand by keys and the operating of a crank or other motor until it comes to a stop, will obviate all the undesirable features of performing multiplication on a key driven machine by the usual method; and like considerations apply to division.

Heretofore there have been machines made for multiplication and division known as crank operated machines. Two well known types of this order are the Brunsviga and Triumphator made under the Odhner patents. In these machines it is necessary for the operator to turn the crank the exact

number of times represented by each figure of the multiplier, and to shift the accumulator mechanism for each place in the multiplier as the proper number of turns have 5 been made. While it requires less instruction to teach an operator to use these machines, their accurate operation requires constant attention of the operator to manipulate the shifting mechanism at the 10 proper time and to give the accurate number of revolutions to the crank for each place in the multiplier. Another well known crank operated multiplying machine is the Millionaire which may be termed a semi-automatic machine. Unlike the above named 15 machines this machine requires only the shifting of the accumulator mechanism for each place in the multiplier, and the setting of a device which determines the number of times the multiplicand 20 is added for each place in the multiplier by operating the crank, making it unnecessary to keep a count of the requisite turns of the crank for each figure in the multiplier as in 25 the above named machines. It still remains, however, for the operator to shift the actuator mechanism and set the controlling device for each place in the multiplier after the crank has been operated. Such a 30 machine might be termed a single order automatic multiplying machine, while this invention relates to a multiple order simultaneous automatic multiplying machine, requiring no shifting of the accumulator 35 mechanism or attention on the part of the operator in turning the crank other than to turn it until it is automatically stopped. While it is possible to perform addition on 40 these machines, the operation is exceedingly slow compared with the multiple order key-driven machine. A later proposed machine is the Detroit multiplier (Horr and Travis Patent No. 1,011,057) in which an adding 45 machine is placed under a multiplying keyboard in which the multiplying keys are set, and thereafter depressed and the keyboard laterally shifted by an oscillating crank. The adding machine is not modified in its 50 mechanism so as to become key set, and to perform addition or subtraction rapidly the adding machine must be bodily removed from under the multiplying keyboard.

Again, while multiplication can be accomplished with considerable speed on a key-driven machine, there are many cases where the crank machine is more rapid. It is therefore obvious that the combined qualities of these two classes of machines, with the objectionable features I have illustrated 55 with respect to the operation of crank machines obviated by automatic control, would produce a most desirable and complete calculating machine. It is to such end among others, that this invention is directed.

60 In order to make the invention more

clearly understood I have shown in the accompanying drawings means for carrying the same into practical effect, without limiting the improvements, in their useful applications, to the particular constructions 70 which, for the purpose of explanation, I have delineated.

In the said drawings—

Figure 1 is a plan view of a calculating machine embodying my invention. 75

Fig. 2 is a side elevation of the same, looking from the right-hand side of the machine, with a portion of the casing removed.

Fig. 3 is a sectional view with certain of the other parts removed, in order to better 80 display the mechanism.

Fig. 5 is a side elevation at the left side of the machine, with the casing removed.

Fig. 6 is a similar view, showing the casing in section, and with certain of the parts removed, to better display the mechanism. 90

Fig. 7 is a similar view, the front portion of the machine being omitted, and parts of the mechanism removed.

Fig. 8 is a vertical section, on a larger scale and of full size, on line VIII—VIII 95 of Fig. 1, the front portion of the machine being omitted.

Figs. 9 and 10 are vertical longitudinal sectional elevations of the front part of the machine, showing the adding and carrying 100 mechanism.

Fig. 11 is a plan view of the machine, with the casing removed, and the stems of the adding keys shown in horizontal section.

Figs. 12 and 13 are transverse sectional views showing portions of the machine, and taken respectively on lines XII—XII and 105 XIII—XIII of Fig. 2.

Fig. 14 is a transverse vertical section of a portion of the machine taken on line 110 XIV—XIV of Fig. 2.

Fig. 15 is a side elevation, looking from the right-hand side of the machine, of the mechanism constituting the automatic control setting device, the casing and cross 115 shafts being shown in section.

Fig. 16 is a detail view in side elevation showing the locking means operated by the automatic control setting device.

Fig. 17 is a plan view of the same. 120

Fig. 18 is a side view looking from the right-hand side of the machine and illustrating the actuating crank mechanism, and a part of the trans-setting actuating devices.

Fig. 19 is a plan view of the same, its middle portion being broken away, and supporting parts being shown in horizontal section. 125

Fig. 20 is a side view looking from the right-hand side of the machine, showing one of the cams for actuating the multiplying 130

mechanism, and main shaft shown in section.

Fig. 21 is a similar view of the shaft, and showing one of the arms for controlling the multiplying mechanism.

Fig. 21^a is a side view showing two of the arms belonging to the neutralizing mechanism.

Fig. 22 is an elevation, partly in section, 10 of a portion of the machine, illustrating the multiple actuating mechanism and its connection with the parts of the adding mechanism.

Fig. 23 is a plan view of a portion of the 15 same.

Fig. 24 is a detail view showing in side elevation, with the shafts in section, the locking mechanism illustrated in Fig. 16, but looking from the opposite side of the 20 machine.

Figs. 25 to 29 are detail views, in side elevation, looking from the left of the machine and illustrating the multiple actuating mechanism and controlling means therefor, in 25 various positions, hereinafter more particularly described.

Fig. 29^a is a rear view of a portion of Fig. 27.

Fig. 30 is a full size side elevation of the 30 multiple actuating mechanism, looking from the right-hand side of the machine and showing the connection thereto with the mechanism of the adding machine.

Fig. 31 is a front elevation, of full size, 35 illustrating the multiple control mechanism, part of the casing being broken away.

Figs. 32 and 33 are vertical transverse sections of the same, on lines XXXII—XXXII and XXXIII—XXXIII, Fig. 31, 40 respectively.

Figs. 34 to 39 are detail views, in side elevation, illustrating the multiple control mechanism, Figs. 35 and 36 being shown as looking from the left-hand side of the 45 machine and the others being shown as looking from the right-hand side of the machine, the parts being shown in different positions hereinafter more particularly referred to.

Figs. 40 and 41 are detail views in side elevation looking from the right-hand side of the machine, illustrating the cipher control mechanism, the parts being shown in different positions hereinafter referred to.

Fig. 42 is a plan view illustrating the 55 column trans-setting mechanism.

Figs. 43 to 45 are side views illustrating the same, in different positions.

Figs. 46 to 48 are detail views showing 60 the same mechanism, and parts connected therewith, in side elevation.

Fig. 48^a is a vertical section looking forward, of a part of one of the frames at the left of the machine, showing also certain 65 supported parts.

Figs. 49 and 50 are right-hand side views illustrating the column trans-setting mechanism, in different positions.

Fig. 51 is a plan view showing a portion 70 of the same.

Fig. 52 shows the end of one of the multiple actuating levers in section, and the sliding dog and frame mounted therein.

Fig. 53 is a plan view of the retaining frame, detached.

Fig. 54 is a cross section on line LIV—LIV of Fig. 52.

Fig. 55 is a plan view of a portion of the mechanism, illustrating the column trans-setting lock.

Fig. 56 is a side elevation of the same.

Fig. 57 is a plan view of a portion of the neutralizing mechanism.

Figs. 58 and 59 are side views of the same, with the parts in different positions 85 hereinafter referred to.

Fig. 60 is a plan view illustrating the multiple re-setting and safety locking mechanism.

Figs. 61 and 62 are detail views showing 90 a portion of the same in left side elevation.

Fig. 61^a is a detail view of the hooked link and a portion of its slotted controlling link. Fig. 61^b is a detail of the locking key lock.

Figs. 63 and 64 are right-side elevations of a portion of the mechanism shown in Fig. 60.

Fig. 65 is a detail view in left side elevation, illustrating the column actuator neutralizing device.

Fig. 66 is a plan view of the same, partly in section.

The principle of the machine consists in causing repeated strokes of an adding 105 mechanism, representing a certain number, to be performed for the proper number of times in each place (units place, tens place, etc.), according to the digits, and places thereof, of another number, and in causing this to be done automatically as to the number of strokes in each place and the changing from one place to another.

In referring to multiple strokes it is not 110 to be understood that multiplication alone is intended. Such strokes may have a negative value, as in division and analogous calculations, and the machine may be employed in a variety of calculations where repeated movements or strokes of an adding mechanism, either positive or negative, are desired.

The operations of the machine comprise: (1) a connection of certain orders of the adding mechanism with the multiple stroke mechanism, so that the said orders, and 125 their respective capacities for accumulation at each stroke, correctly represent a factor (say the multiplicand) of the problem; (2) a setting of the mechanism which controls the multiple stroke mechanism, so 130

that it represents another factor of the problem (say the multiplier), in causing the first factor to be automatically repeated the proper number of times and in the proper places, according to the digits, and the places thereof, of the second factor; (3) an actuation, by hand or other power, of the multiple stroke mechanism, for a cycle during which the multiplication, division, or other problem, is automatically performed, and at the end of which cycle the correct result is shown by the accumulator numeral wheels of the adding mechanism.

During one such complete cycle of operation various subsidiary operations occur. Preliminarily the adding machine is a multiple order, key-driven mechanism capable of light and rapid action for purposes of addition and subtraction and the first operation is to adjust the machine for multiple stroke action such as multiplication or division, so that the orders of the adding mechanism are connected with the multiple stroke mechanism, which is accomplished by an automatic control setting device. By this operation the key driven mechanism is converted to one which is key set. The next operation is to determine the additive degree, or length of stroke, of the multiple stroke mechanism for each order of the adding mechanism which is to be operated (according to the digits and places thereof of one factor), which is accomplished by setting a multiple order actuating mechanism, for instance by depressing finger keys of the adding mechanism to correspond with the said factor. The next operation is to provide for a certain number of strokes (or no strokes) of the multiple stroke mechanism in certain digital places, according to the digits and places thereof of the other factor, which is accomplished by a setting of the multiple control mechanism. As a precaution against mismanipulation it is preferred that the multiple stroke mechanism shall be locked against operation when the adding mechanism is free and until all of the said adjustments and settings have been completed. The above operations having been performed and the machine being ready for a multiple stroke calculation, it may be unlocked so as to free the hand or power actuator, and this is accomplished by a key connected with the locking and releasing devices of the various parts. It is now possible to begin and quickly perform the said cycle of operation. First, the multiplicand, or factor set on the adding machine keyboard is added on the numeral wheels thereof as many times as there are units in the left hand digit of the multiplier or factor set on the multiple control mechanism, and in places, or orders to the left corresponding to the place above units of

said digit of the multiplier. The multiple control mechanism now automatically causes a trans-setting to the right, place for place and order, for order, of the entire multiplicand; that is to say, the connections between the adding mechanism and the multiple stroke mechanism which represent the multiplicand are so trans-set one place to the right. This is accomplished by the column trans-setting mechanism. The multiple control mechanism now causes the multiplicand to be repeated in this new place as many times as there are units in the second digit of the multiplier. Such operations continue until the multiplier is exhausted, when the machine comes to rest in locked condition with the correct result, the product of the two factors in the case supposed, visible on the numeral wheels of the adding machine. If the multiplier contains an intermediate cipher the multiple control mechanism is set for a cipher in that place, so that the automatic operation of the mechanism shall continue on to the digits of the multiplier which are at the right of such cipher. But while the trans-setting of the multiplicand thus takes place to the right past the place of the cipher it is not repeated in the place of the cipher. This is accomplished by the cipher control mechanism.

Before describing the automatic multiplying mechanism I will first make sufficient reference to the known comptometer mechanism to make understood how the multiplying mechanism is or may be connected with an accumulator or adding mechanism to coöperate therewith for multiplication and other calculation; and it is to be understood that my invention, in respect of improvements in the multiplying mechanism, is not confined to the use of any particular accumulating or additive devices, providing that the same are suitable for the purpose. In respect of other features of invention the improvements consist in the combination of the multiple stroke mechanism with accumulator or adding mechanism having certain special characteristics, as pointed out in claims therefor.

Following is a description of the particular adding mechanism, including so much of the accumulating and canceling mechanism as is necessary to set forth, to which the invention is in this instance applied.

The adding or accumulating mechanism, (Figs. 9 and 10.)—Referring to the drawings, 1 indicates the vertical longitudinal plates constituting a part of the frame of the machine, and 9 the top plate thereof. The frame preferably comprises vertical side or retaining plates, such as are shown at 1, 125 and similar intermediate or division plates, one of which is arranged in each of the spaces between the numeral wheels 2. All

of these vertical plates are rigidly connected by suitable cross bars or tie rods 3 to form a main frame.

The accumulator mechanism, to and including the numeral wheels, is caused to be actuated, in the calculating operation, by denominational series or ordinal sets of finger keys 4 mounted to reciprocate vertically in guide apertures or bearings in the 10 top plate 9, and the lower end of each key stem is pressed upward by a lever 5 and spring 6 carried by lower frame parts 7.

For convenience I will recapitulate certain of the parts, and their functions, known 15 in and by the prior patents above mentioned; but it is not necessary to an explanation of the present invention to repeat all of the description and illustration of said patents.

20 The principal parts are the following: Column actuators or segment levers 8 pivotally mounted on a cross-rod 51 on the frame 1, and yieldingly held up by accumulator actuating springs 10; odd and even 25 stop levers 11, 11', 12, 12', each of which may comprise two separate co-acting parts, as shown, and which are pivoted to the rear and front of the frame on cross pivots or rods 13, 14; stop detents 15, 16 carried by 30 the lever parts 11', 12', to engage with the coarse spaced teeth 17 on the column actuator and arrest the downward movement of the latter; accumulator pinions 18 (Fig. 9) mounted on the cross pivot accumulator 35 shaft 19 and engaged and turned by the column actuators; accumulator ratchets 20 fixed to the pinions 18; lantern wheels 21 having pawls pivoted thereon and arranged within the ratchets, whereby the ratchets 40 turn backward freely but on their forward movement rotate the lantern wheels by means of the said pawls; a back stop pawl 22, and a locking detent 23, for each lantern wheel, the locking detents being spring 45 pressed away from the lantern wheels and being pushed into engagement by roller studs 8' on the column actuators; intermediate gears 24 on the intermediate shaft 25 and meshing with gears 26 (Fig. 6) 50 attached to the lantern wheels, engaging and driving the numeral wheel gears 27; carrying pinions 18' attached to the accumulator gears and meshing with and driving carrying gears 28 on the cross pivot carrying 55 shaft 29; carrying motor springs encircling the shaft 29 and connecting the carrying gears yieldably with rotary escapements 30 on the shaft 29; two-armed carrying cams 31 (Fig. 10) fixed on the said escapements 60 and given, by means of the said carrying motor springs and escapements, a half revolution at each half revolution of the carrying gears or whole revolution of the carrying pinions (see Felt Patent 996,009, Sheet

3); carrying levers 32 each of which is pivoted on the cross pivot shaft or rod 33 and is arranged in line with the lantern wheel in the next higher order of accumulator mechanism, said carrying levers being raised by the carrying cams at each half revolution 70 of the latter; carrying pawls 34 pivoted, as are the locking detents, on the carrying levers and operating on the pins of the said next higher lantern wheel to move the latter and other parts of its accumulator mechanism one step at each carry; carry-detaining latches 35 to enable two or more keys in different orders to be simultaneously depressed without losing a carry; cam-actuated three armed detents 36 (Fig. 4) for locking 80 the carrying levers; and canceling stops 37 for positioning the accumulator mechanism and numeral wheels in canceling, mounted on a rock bar 38.

The machine is of the duplex type; that 85 is to say, two or more keys in different orders may be simultaneously depressed and each will give its proper and full effect in the accumulation. To this end the carrying mechanism is adapted to permit prime 90 actuations of the accumulator mechanism in a plurality of orders simultaneously. That such full effect of the depression of the key of lower order be attained it is necessary that any carrying, which may be due to take 95 place from the lower numeral wheel to the higher numeral wheel, shall not be lost by reason of the higher numeral wheel having such forward motion that the carrying mechanism may not affect it. The latch 35 100 is pivotally mounted on the cross rod 39 of the frame and extends over the carry mechanism, resting at its inner or rear end on the stud pin 40 of the column actuator 8. The latch has a tooth 41 which is adapted to 105 engage either (whichever may first encounter it) of the two projections 42 on the rotary hub or sleeve of the carrying mechanism. When any key of the order to which a carry is to be made is struck the actuator 110 8 of that column and its pin 40 moves down, allowing the latch 35 to drop where its tooth 41 may engage a projection 42 and arrest any rotation of the carrying devices which might at that time be ineffective. The carrying 115 devices continue to be so held until the column actuator 8 rises, and the key and numeral wheel of the higher order have completed or substantially completed their operation, whereupon the pin 40 lifts the latch 35, and releases the carrying mechanism, and allows the latter to be actuated by its carrying spring to effect the proper carry 120 which may be due to occur. The carrying mechanism of each column or order is provided with a set of the described parts 35, 40, 41.

43 is the latch releasing device (Figs. 9

and 10), preferably a swinging release bar which positively releases the latches 35 and connected carrying mechanism. It is formed with arms 44, pivoted to the frame on the cross rod 39 and is arranged to engage the tail pieces 45 of the latches 35 at a point below the pivot cross rod 39 of the latches and force them backward to lift the latch teeth 41. 46, 46' (Figs. 2, 3 and 6) indicate 10 links which pivotally connect with the arms 44 of the release bar 43, above the pivot rod 30. The link 46 at the right side of the machine connects with the forward end of a release lever 49 at 50. The link 46' at the 15 left side of the machine (Fig. 6) is connected at 67' with the leftmost canceling stop 37 on the rock bar 38, thereby equalizing the action and pressure of the release bar 43 on all of the latches 35. The principal parts of the above described carrying mechanism are more particularly set forth in Felt Patent No. 960,528.

The canceling means, (Figs. 2, 3, 6, 9) whereby the numeral wheels are reset at zero, 25 comprises a canceling actuator, or cancellation controlling means, consisting in this instance of a cross rock shaft 52, crank handle 53 and slotted cam 54. These parts operate on a canceling device comprising a segment lever 30 55 actuated by the slotted cam; a canceling pinion 56 (Fig. 3) on the canceling or intermediate shaft 25 (Figs. 9 and 10); and means by which said shaft may rotate the intermediate gears 24 when the shaft is in a 35 certain position relative to the gears. The canceling means also comprises devices effecting a one-space adding movement of the column actuators, consisting of a transverse bar 57 adapted to depress the column actuators 40 tors one space and give a one-space adding movement to the accumulator mechanism, which bar is reciprocated vertically by the slotted cam through the medium of arms 58, which carry the bar at their ends and are 45 pivoted at 59 to the frame 1. All of these parts are or may be similar to those set forth in my said patents.

The canceling operation, (Figs. 2, 3, 6, 9 and 10.)—For accuracy in bringing the 50 numeral wheels from their various positions all to the "0" position, those of the second and higher orders are first brought to the "8" position, and the units wheel is brought to the "9" position; then the cross bar 57 55 and the column actuators having been depressed one step, rise and move all of the wheels one step. The wheels of higher order than units to the "9" position and the units wheel immediately after to the "0" position, the said movement of the units wheel being detained in a known manner by a slightly elongated tooth 61 on its canceling stop 37 (Fig. 10), and causing the carrying mechanism to operate, successively but

practically instantaneously, across the machine from right to left to bring the said wheels of higher order to the "0" position and complete the canceling operation. Stop studs 60 (Fig. 6) one on each of the carrying pinions 18', engage the under side of the 65 stops 61 on the canceling stop levers or arms 37. The latter are affixed to the said transverse canceling stop rock bar 38 mounted to oscillate in the lower part of the frame. When the stops 61 are rocked forward into 70 the paths of the stop studs they are adapted to arrest the accumulator mechanism in such position that each numeral wheel of higher order than units is held positively in the "8" position, the units wheel stopping at the 75 "9" position by reason of a little later (36 degrees) positioning of its stud on its pinion.

Referring to Fig. 6, 62 is an arm extending from the rock bar 38 and having affixed thereto a pin 63. This pin is engaged by a 80 jaw 64 at the forward end of a lever 65 pivoted at 59 to the frame of the machine. 66 is a spring connecting the lever 65 with the frame of the machine and acting to pull the forward arm of the lever, and the rock 85 bar 38, backward and downward and the rear arm of the lever upward. 68 is a link pivoted at 69 to the rear arm of the lever and at 70 to the rear stop arm 71 of a bell crank lever, which is pivoted at 72 to the frame 90 and has a forward cam arm 73 formed with a cam 74 (Fig. 6). The bell crank lever is adapted to be turned forward until the pivot point 70 passes a little forward of the straight line of the points 69 and 72 and the 95 arm 71 engages the rear side of the link 68 or other suitable abutment, whereupon the parts form a toggle lock against the pull of the spring 66, and, the rear arm of the lever 65 have been depressed by the described 100 movement of the parts 71 and 68, holds the canceling stops 61 in the paths of the carrying pinion stop studs 60. The said arms 58 which carry the canceling cross bar are 105 formed with cams 75 (Figs. 2 and 3) which 110 are depressed by dolly rolls 76, 76' at each side of the machine, which rolls are connected with and oscillated by the canceling shaft 52.

The bell crank lever is turned forward as 115 above described by the dolly roll 76' at the left of the machine, which on the backward movement of the canceling handle operates on the cam 74 as well as on the cam of the left arm 58 above mentioned. When the 120 canceling handle lever 53 is turned forward and the dolly roll backward the said dolly roll 76' leaves the cam 74; but the parts 71, 68 and 65 remain in their toggle locked position, with the stops 61 in engagement with 125 the studs 60, until the handle 53 reaches its forward normal position and the dolly roll presses upward and backward slightly on the

link 68. Thereupon the link 68 is turned over backward and the pivot 70 carried rearward across the toggle line, the toggle lock is broken and the spring 66 instantly releases the parts to the position shown in Fig. 6 and releases the stops 60 from the carrying pinions, and from the accumulator mechanism connected with said pinions. In the construction illustrated this instantaneous tripping of the parts occurs at substantially the end of the operative part of the return or forward movement of the canceling actuator handle 53, and this is the time preferred for such tripping. At substantially the same time the column actuator cross bar 57 is raised by the springs 77 (Fig. 4) and the column actuators 8 rise and cause the numeral wheels to be turned one step, which, with the final carrying, effects the cancellation or zeroizing. The dolly roll 76 also acts to depress and release the release bar lever 49, the latter being formed on the upper edge of its rear arm with a cam surface 49' (Figs. 2, 3) on which the roll 76 operates for such purpose. This canceling, clearing or zeroizing mechanism is more particularly described in Felt and Turck Patent No. 1,072,934.

With the said accumulating or adding mechanism, or with other accumulating mechanism suitable for the purpose there is combined a multiple stroke mechanism as hereinafter described. The said accumulating mechanism may be set to represent potentially one of the numbers or factors which are to be multiplied together, though such factors may not appear at that time on the numeral wheels of the accumulator mechanism. The further object to be attained is to so construct and arrange the multiple stroke mechanism that it may be set and controlled to represent potentially the other factor or multiplier of the product to be obtained; and to so connect it with the said accumulator mechanism that, when operated, it will actuate each order of the accumulator mechanism, representing a denomination of the multiplicand, such number of times, according to the denominations of the multiplier, as to accumulate the sum of the products of the multiplicand by each denomination of the multiplier. Thus the additive length or degree of stroke represents the multiplicand and the number of strokes represents the multiplier.

Suppose that 456 is to be multiplied by 123: the machine is adjusted for multiplication by connecting the actuating means of the accumulator mechanism, in the various orders thereof, with the corresponding orders of the multiplying mechanism. The multiplicand is set on the accumulating mechanism by depressing the 4, 5 and 6 keys. This setting will be in the tens of thousands

(5th order), thousands (4th order), and 68 hundreds (3rd order) columns, according to the number of places in the multiplier, so that the product may be accommodated on the numeral wheels with the units of the product in the units order. In effect such 70 setting is a part of the multiplication process and has multiplied 456 by 100, and the first actuation of the numeral wheels when their column actuators are released by the multiplying mechanism will show 45600. The 75 construction of the multiplying mechanism is such that the depression of the said keys in the orders named will set the corresponding orders of multiplying mechanism so that, when actuated, its 5th order will stop 80 the corresponding accumulator numeral wheel at 4, its 4th order will stop its wheel at 5 and its 3rd order will stop its wheel at 6; and each cycle of movement of the multiplying mechanism, while its connections 85 with the accumulator mechanism are as above stated, would add 4, 5 and 6 on the said numeral wheels of the 5th, 4th and 3rd orders, respectively, amounting to an accumulation of 45600 at each cycle of movement. In the example given, the multiplier being 1, only one such cycle is required.

Before the multiplying mechanism is thus actuated, controls for its various orders are set, so that three of its orders (representing 95 123 in the case supposed) may successively have first one cycle of movement, and then two cycles of movement, and then three cycles of movement. And the said controls also cause the connections between the respective orders of multiplying mechanism and accumulator mechanism to shift, or be trans-set, successively and automatically to the right; so that, after the one-cycle movement, the operative connection of the multiplying mechanism with the 5th, 4th and 3rd orders of the adding mechanism will be released, and the 4th, 3rd and 2nd orders will become connected, each respectively with the same additive degree of movement which the 5th, 4th and 3rd orders formerly had, so that now the same digits, 456, will be accumulated at each stroke in this new setting. This setting continues during the two-cycle movement; and after the two-cycle movement has been completed the said connections will again be trans-set, each one place to the right, the 4th, 3rd and 2nd orders becoming disconnected and the 3rd, 2nd and 1st becoming connected, and so remaining 110 during the three-cycle movement. This shifting of connection under the said controls is such that the highest connected multiplying lever will continue to add 4 at each cycle of movement, in whichever column or 115 order of accumulator mechanism it is acting; the next higher lever will continue to add 5, and the lower lever will continue to 120 125

add 6. The additive degree of movement, to add 4, which the highest multiplying lever originally has is thus preserved but trans-set to the right from lever to lever, until the requirements of the example have been fulfilled. The same is true of the other multiplying levers which have been set. During such successive accumulations or additions the accumulator mechanism acts in a known manner, carrying from wheel to wheel from right to left. The result is a showing of 56088 on the numeral wheels. The process is a mechanical and automatic repetition of additions in the ordinary process of multiplication when worked from left to right, beginning with the ten thousands and ending with the units. Thus, the first one-cycle movement accumulates 45600; the second two-cycle movement accumulates 9120 more; and the final three-cycle movement accumulates 1868 more, the total being the correct product and shown on the numeral wheels.

In the above operation the principal functions to be automatically performed are to control the multiplying levers so that they will make exactly the required number of strokes in all the denominations of each setting, to trans-set the additive degree of movement of each lever to the next lower lever at the end of each cycle of movement, and to prevent any accumulation on the numeral wheels of the adding mechanism during the period of trans-setting. It may here be stated that to preserve the continuity of the setting of the multiplier there must be operations of the control mechanism, for any intermediate ciphers which it contains must be trans-set, and a trans-setting of the multiplicand past such cipher; and for this purpose the multiplying levers make a stroke. But such stroke, representing a cipher, must not actuate the adding mechanism. This is preferably accomplished by giving eleven steps or positions to the multiple control mechanism, represented on its indicators by 9, 8, 7, 6, 5, 4, 3, 2, 1, 0 and a blank. If an indicator be set at 9 any set multiplying lever will give nine strokes, and this capacity may then trans-set to the next lower lever. So of all the other digits, according to their value. The trans-setting of all the levers occurs simultaneously after the stroke from 1 to 0 and after said stroke the adding mechanism is disconnected, by the cipher control mechanism. For example, in multiplying 456 by 1002, the 456 is caused to appear once on the adding numeral wheels in such position as to represent 456000. The three multiplying levers set to give 456 are now to be trans-set three places to the right without actuating the adding mechanism, and then they will cause its actuation twice for a total value of 912. The multiple control indicators, with which the mechanism functionally corresponds, successively show dur-

ing the strokes of this operation (the blank spaces of the indicators being represented by dashes, and it being understood that all indicators which are not set show blank spaces)

The product 456912 appears on the adding numeral wheels at the end of the strokes to - - - 0, and during the last stroke to - - - the whole machine resets itself in normal position.

In the adding mechanism all ciphers are, in the usual manner, represented by unset keys. The corresponding multiplying levers remain set at normal, or what may be called neutral position, and have no additive movement. But this neutral setting is trans-set as are all digits, so as to preserve the continuity of the multiplicand. An important feature of the invention is the automatic taking care of intermediate ciphers in the multiplier, so that the continuity of both factors is preserved, and that of the multiplicand in any trans-setting, and the operation of the machine as a whole is continuous without inaccurate accumulation.

The foregoing explanation of what the machine is designed to perform will aid in understanding its construction and operation, which will now be further described.

The multiple stroke mechanism, (Figs. 22 to 30.)—Arranged substantially in line with each order of adding mechanism is a multiplying lever whose function it is, when connected with its corresponding column actuator 8 and oscillated in vertical longitudinal planes by a main rock shaft 100, to depress the column actuator for a greater or less distance, according to the setting of the lever, and thereby cause an accumulation on the adding mechanism as the column actuator rises to normal position. Each lever consists of two independent but connectible parts pivoted on a cross rod 101 of the frame. One of these parts, which for convenience is termed the rack lever, has a rearward arm 102 formed with an inner toothed rack 103 by which it may be locked in any of ten different positions to its companion lever part, with an outer toothed rack 104 by which it may be temporarily locked to a lever part in the next higher order, with a tooth 105 by which a cross stop bar 106 of the frame arrests it in normal position, and with a ratchet 107 by which it may be held when set by an adding machine key (Fig. 22) at any one of nine distances from

the bar 106 so as to be capable of accumulating in its order any multiplicand digit from 1 to 9 at a stroke, the number of strokes representing the multiplier. The said racks and 5 ratchet are formed on arcs concentric with the lever pivot, and their teeth are related to the nine keys of the order of the adding machine. The lowest ratchet tooth is related to the 1 key and ninth tooth to the 9 key, 10 and the lowest rack notches are related to the 1 key and the ninth (inner and outer) rack notch is related to the nine key. The other lever part, which is termed the dog lever, is composed of two rearwardly extending 15 arms 108 between which a locking dog 109 is slideable radially, 110 is a roll mounted on the dog lever, each of such rolls being engaged from below by a cam 111 fixed on the main rock shaft 100. 112 and 113 indicate 20 springs by which the lever parts are pulled, rearward and downward, thereby tending to seat the tooth 105 against the bar 106, to elevate the forward lever arm 114, and to hold the rolls 110 against their cams. 25 The arm 114 has a lateral lug 115 by means of which the multiplying lever is adapted to be connected with its column actuator. 116 is a pawl, one for each ratchet 107, pivoted to the frame at 117, pressed toward the 30 ratchet by a spring 118 and formed with a tail 119. 120 is a transverse rock bar provided with projections 121 adapted to depress the tails 119 and release all of the pawls from their ratchets (Fig. 29) after 35 the desired rack levers have been set for operation.

The normal position of the cams 111 is at the top or extreme of their throw, (Fig. 22) supporting the rolls 110 and dog levers in 40 their most elevated position. Assuming that the rack levers have been connected with their column actuators, as later explained, and that 456 is to be multiplied: The 4, 5 and 6 keys of the adding machine 45 are depressed, in successive orders, to the left of the units column according to the number of places in the multiplier. This elevates the rear arms of the corresponding rack levers 102, which were resting with 50 their teeth 105 on the cross stop bar 106 (Figs. 4 and 8) and were held down by their springs 113, and they will be held up by the pawls 116 which will engage respectively the fourth, fifth and sixth notches of the 55 ratchets 107. While in these positions the said rack levers are to be locked each to its companion dog lever by the dogs 109. Each dog slides in slots 122 in the dog lever, being held in place by a sliding retaining frame 123 (Figs. 52-54). A spring 124 presses the frame and dog outward. Each dog has a left hand outwardly directed tooth 125 by which it may engage the inner rack 103 of its companion rack lever and 60 a right hand inwardly directed tooth 126

(Fig. 23) by which it may engage the outer rack of the rack lever in the next order to the right. The frame 123 is formed with two ratchet teeth 127, engageable by a pawl 128 pivoted at 129 on the dog lever, and having an outwardly extending tail 130. A transverse rock bar 131 pivoted in the main frame has fixed thereto (Fig. 30) a series of L-shaped arms 132 the forward ends of which are adapted to depress the pawl tails 130 when said bar is rocked forward, thereby disengaging all of the pawls from either of the teeth 127. The normal position of the parts is neutral (Fig. 4), with the pawls in engagement with the inner of the two 75 teeth 127 and the dog teeth 125 and 126 out of engagement with either rack. This position allows of the setting of the rack levers as above described. The function of the outer one of the teeth 127 is to temporarily hold, against the pressure of the spring 124, the outer dog tooth engaged with the next lower rack lever during a trans-setting 80 stroke. As soon as the rack levers have been set as above described the initial movement of 85 the crank handle causes the bar 131 to be rocked forward, which releases the pawls 128 against the pull of their springs 133 and allows the springs 124 to force the dogs 109 into engagement with the inner racks 90 103 (Fig. 25) of their companion rack levers which have been so set. Immediately thereafter the bar 120 is rocked rearward so as to release the pawls 116 (Fig. 29) from the ratchets 107. This leaves the multiplying 100 levers free for vertical vibration, the companion rack lever and dog lever being locked together and working as one lever, being alternately pulled down by the springs 112 and 113 and elevated by the cams 111, 105 and the arms 114 which drive the adding mechanism rising as the rear ends of the levers are let down by the cams. As the set multiplying levers are so vibrated the tooth 105 of each one descends to the stop 110 bar 106 and rises therefrom, each lever having the particular additive degree of stroke for which it has been set. Thus, while the cams 111 all have the same throw and allow the multiplying levers to start downward 115 from the same height, each lever has its own additive throw depending on the set distance of its tooth 105 from the stop bar 106. The stopping of the multiplying lever at the top limit of the cam throw represents the stopping 120 of the column actuator at its low point (according to the key which was depressed to set it); and I may here state that the stop levers and stopping detents, or their equivalents, usual in adding machines to 125 limit the downward throw of the column actuators, have no necessary function in this machine (when set for multiplication) to arrest the column actuators in accumulation, while the multiplying mechanism is 130

connected with the accumulator mechanism. But the invention is not limited to dispensing with the use of such stops. It will be understood that, while the operation of only one multiplying lever is above referred to, all set multiplying levers connected with column actuators rise and fall together, but each gives, at each oscillation, the particular extent of movement to its connected actuator, and consequent accumulation, which is due to the key the depression of which has adjusted the two parts of the multiplying lever; and the number of such individual accumulating oscillations in each cycle of movement, and the number and successive order of such cycles, are according to the setting and operation of the control devices hereinafter described.

It will be understood that upon setting the handle 134 (Fig. 1) to Mul. or Div. (as later explained) all column actuators are normally connected with their multiplying levers, and have to be specially disconnected at the bottom of the stroke to allow them to rise independently of the levers and under the powers of their own springs, or to prevent accumulation for a cipher in the multiplier. But only the levers which have been set at 1 or more partake of the vertical vibration above described, because, when the dog pawls 128 are tripped, all rack levers which have not set are locked by their dogs in the neutral notch 135. The dog levers so locked being then at their highest point and their companion rack levers being down against the stop bar 106, these unset and neutrally locked rack and dog levers remain immovable (until a trans-setting) and their cams 111 turn inoperatively under their rolls 110.

Although the dog levers 108 are always pressed toward their jaws 111 by the springs 113, it is preferred that a top positive stop be provided for the multiplying levers when their two parts are locked together and they are in rapid vibration, in order to insure against any upward overthrow. Accordingly one of the cross tie rods of the frame, which is located just above the dog levers when they are at the top of their throw, is provided with tubular spacers 136 of eccentric or cam form. These spacers hold the longitudinal frame plates at the proper distances apart. Before they are clamped against the frame plates by the end screws of the tie rod they are rotated and thereby adjusted so that each of the dog levers will touch the bottom surface of the spacer above it at the instant when the lever is at the top of its throw (Fig. 22).

From the above explanation of the preferred mode of operation it is seen that the rack lever spring 112, the dog lever spring 113 and the column actuator spring 10 all

cooperate on the said three parts, when they are connected together, to press the column actuator and front multiplying lever arm upward and the rear multiplying lever arm downward. The front ends of the rack 70 levers are normally connected with the column actuators (Fig. 22) by the links 139 (unless the machine is set for addition). After the column actuator has been disconnected at the bottom of the stroke (as 75 later explained) it will normally spring upward at once, followed by the front multiplying lever arm as the cam lets down the rear multiplying lever arm. This mode of operation gives to the mechanism of the 80 adding machine the same natural action as it has under finger manipulation, and for which it was constructed.

Each cam 111 is formed with an outer concentric surface 137 and an inner concentric surface 138, each of these surfaces having a circumferential length of about eighteen and one-half degrees (Fig. 20). These concentric surfaces give a dwell, at the top and at the bottom of the stroke, to 90 the multiplying levers. While they are thus stationary the main rock shaft continues to move and, by other arms and cams keyed thereon, causes such mechanical movements as are necessary or desirable to take place 95 while the multiplying levers are stationary, including the trans-setting of its additive length of stroke from one multiplying lever to its next lower lever.

Key set and automatic control connecting device, (Figs. 15 to 17).—This device connects and disconnects the adding mechanism and the multiplying mechanism, and is operated to convert the key driven machine to a key set machine, and vice versa. In the 100 particular construction illustrated it connects the column actuators 8 with the lateral lugs 115 of the multiplying levers. Each column actuator is provided with a link 139 pivoted thereto at 140, pressed rearward 110 by a spring 141 and formed with a jaw 142 on its rear side. In the normal position of the rack levers, with their rear arms depressed against the stop bar 106 and their front arms 114 elevated, the lugs 115 will be 115 exactly opposite to the jaws 142, and it is at this time that the jaws are swung rearward to engage the lugs. Each link 139 has fixed thereon a lateral pin 143 the rear side of which is engaged by one of a series of arms 120 144 fixed on a transverse rock bar or shaft 145, which is pulled to turn forward by a spring 357 (Fig. 40.). When this shaft is rocked forward the arms 144 swing backward releasing the pins and permitting the 125 springs 141 to force the jaws of the links into engagement with the lever arm lugs 115, whereby each upward and downward movement of the multiplying levers causes a movement for the same distance of the 130

column actuators and a corresponding accumulation on the adding machine. It is to be understood, however, that such multiplying lever will have no vertical movement 5 (as hereinafter explained) unless a key of the adding machine, and in the order to which the lever belongs, has been depressed subsequent to the said connection of the lever and column actuator. If a 9 key has 10 been depressed the lever will thereafter, during the performance of the example, have the capacity of moving the column actuator down for a distance which will give an accumulation of 9 in that order (when the 15 column actuator rises) at each stroke, until the multiple control mechanism causes the lever to cease such operation. If a 1 key is depressed the column actuator will be moved by its multiplying lever a short distance down, and will accumulate 1 at each 20 stroke. If no key be depressed in an order the multiplying lever of that order will remain inactive; except that in the course of the performance of an example a setting 25 may be given to such originally inactive lever by the trans-setting mechanism, in which case the lever will become active.

146 is an angle lever pivoted at 147 on the main frame and formed with cam slots 30 148 and 149 (Figs. 15 and 6). The cam slot 148 engages a roll 150, fixed on a forward arm 151 of a lever which is pivoted on the journal of the rock shaft and has a rear arm 152 which engages the top of the rear 35 part of the rock rectangular eccentrically pivoted shaft by a lip 153. The rearward arm of the angle lever is connected by a link 154 with a setting segment 155 pivoted on a cross rod 156 of the frame so as to swing in 40 vertical longitudinal planes just below the rear part of the casing. It is provided with the projection 134 extending through a slot 157 in the casing, which limits the play of the segment and affords the handle by 45 which the segment may be set at will. On the exterior of the casing by the slot 157 are marked a rear, a front and an intermediate position for the setting segment. These marks may conveniently be respectively Add. Div. and Mul. (Fig. 1). When 50 the handle is at Add the rear part of the slot 148 has thrown the arm 151 upward and the lip 153 has rocked the shaft 145 rearward, and the arms 144 forward against the pins 55 143, thereby holding the links 139 away from the lugs 115. In this position the adding mechanism is disconnected and becomes freely key driven, to be used at will for rapid addition and subtraction. When the 60 handle is at Mul. the middle part of the slot 148 has caused the arms 144 to swing rearward and allow the jaws 142 to grasp the lugs 115, in which position the machine becomes key set. Any setting of the adding 65 keys is maintained by the pawls 116, and

thereafter by the dogs 109, as already explained.

It is preferable that the column actuator return upward by the power of its own spring 10, and independent of the multiplying lever. To this end all of the links 139 are disengaged from the multiplying lever arms 114 at the bottom of the stroke. 158 is an arm keyed on the rock shaft 100 and having a lateral pin 163 which enters a slot 75 159 in an arm 160 (Fig. 30), the arm being mounted to turn on the hub of the fixed arm. The rock shaft and arm give to the pin a throw greater than the angle represented by the slot (by about 18.5 degrees) 80 so that the pin throws the segment alternately forward and backward. 161 is a link pivotally connecting the arm 160 with an arm 162 depending from the transverse rock shaft 145, which is mounted in the frame 85 to extend across all of the orders of adding mechanism, so that the oscillation of the main rock shaft (which depresses the front ends of the multiplying levers on its forward throw) is accompanied by a detachment 90 of the links 139 near the end of each forward throw of the pin 163 and arms 144, (as seen in Fig. 30), and by a release and backward movement of the links to re-engage with the multiplying levers near the 95 end of each rearward throw of the pin 163. However, the said links are also disengaged from the multiplying levers to prevent accumulation for a cipher in the multiplier, as later explained. 139' is a pin fixed on the 100 column actuator and arranged to arrest the lower arm of the pivoted link 139 and thereby prevent the upper end of the said link 139 from springing too far rearward when it is released from the multiplying lever 105 and the arm 144 has been swung rearward and the column actuator has sprung up relative to the multiplying lever, or the end of the multiplying lever has been depressed relative to the column actuator in the operation of the cipher control. 110

Negative operations.—In division and other negative operations the factor represented on the adding machine is repeatedly diminished by a certain number, such as the 115 divisor, until the remainder will no longer contain it. Thereupon the stroke control mechanism must be returned to zero, in those denominations or orders in which it has been repeating the complement of the 120 said number, and this return must be made by the operator when the crank handle is at or near a certain point. This position of the handle is signaled to the operator, in each rotation by a notch 164 (Figs. 6 and 15) in 125 the crank wheel 165 which is adapted to be frictionally engaged by a projection 166 on a lever 167 which is mounted on a fixed pivot 59. The projection is pressed toward the 130 wheel by a spring 169. The rear arm of the

lever is provided with a roll 170 on which works the cam slot 149 of the angle lever 146. When the slotted arm of this lever is thrown to its rearmost position the depression of the front end of the slot allows the roll to swing down far enough to allow the projection 166 to enter the notch 164, thereby giving a slight bump which the operator feels through the handle and which is or may be a friction stop or check tending to arrest the handle. If at the same time the operator sees that the remainder will not contain the divisor again he adjusts the multiple stroke control mechanism by shoving forward the slide 293 of the highest control, which has been in operation, which has the effect of stopping the operation of said highest control mechanism and allowing the next lower control to begin its operation (which is in effect a transsetting of the subtraction process one place to the right) and causing the divisor to be repeated (by repeating its complement) further to the right. The parts are in this position when the handle 134 is set at Div. During this extreme forward setting the links 139 are left connected with the multiplying levers, the same as in the intermediate Mul. position, the forward half of the slot 148 being concentric with the pivot of the angle lever.

The remainder for the time being appears on the adding wheels at each turn of the crank, about one third of a turn before the signal is felt. This gives time for the operator, after seeing the remainder, and that it is smaller than the divisor, to be prepared for the signal and stop the crank, even during rapid cranking, without overrunning the point at which the then active control can be pushed forward to 0. This arrangement increases the available speed of the machine.

The actuating crank mechanism, (Figs. 18 to 21*).—The multiplying mechanism is locked against operation until the handle 134 has been set at multiplication or division; until a key has been depressed on the adding keyboard; until a control device for the multiplying mechanism has been set; and until a release key 171 has been depressed. The canceling handle 53 must also be in its normal forward position. But the details of these locking means are left for later explanation.

55 The crank or power shaft of the multiplying mechanism is shown at 172, extending transversely across near the front of the machine and mounted in suitable bearings on the frame. From this shaft which is, in the machine illustrated, rotated rearward by a crank handle 173, an oscillatory movement is transmitted to the main operating shaft 100. From this rock shaft 100 most of the operations of the multiplying mechanism are caused to be performed. The crank

wheel 165 is mounted on the left end of the power shaft, a wrist pin on which wheel is connected with a pitman 174, pivoted at 175 to a swinging arm 176. A toothed rack 177 meshing with the top of a toothed segment 178 keyed on the rock shaft 100 is also pivoted at 179 to the said swinging arm. The rack 177 is guided by a frame 180 provided with rollers 181 which hold the rack in engagement with the segment. The said frame 175 is preferably pivotally connected with the main shaft so as to have a slight movement concentric with the shaft and accommodate and give ease of motion to the rack, which connection may be by bearings 182 at each 80 side of the frame, which surround a hub of the frame or a collar on the shaft.

The said swinging arm is pivoted on the main frame at 183 and has attached thereto a parallel plate 184, giving to the arm a bifurcated upper end. In this bifurcation the pitman is pivoted. The rack 177 is vertically adjustable on the swinging arm by having its pivot mounted in slots 185 where it is clamped by a nut 186. By this means 90 the angle of rocking of the shaft 100 may be accurately determined. The shaft 172 is provided with a ratchet 187 fixed thereon, which is constantly engaged by a spring ratchet back stop pawl 188 (Figs. 2, 3, 63). 95 Fixed on the shaft is a tooth 189 which is engaged, except during the operation of the multiplying mechanism, by a pawl 190. The power shaft is thus held locked during any desired use of the adding machine alone, 100 and until a multiple stroke example has been set up on both the adding machine and on the multiple control mechanism. The said pawls are pressed toward the ratchet by a connecting spring 191.

When at the beginning of an example the power shaft is started to be turned rearwardly its first effect is to turn the main cam shaft forwardly for a short arc from the position shown in Fig. 22. This causes certain movements before the rearward rock of the cam shaft begins and the rear ends of the multiplying levers begin to descend. First, the rock shaft 131 is turned forward to release the dogs and allow them to spring outward. This is accomplished by a toggle through which the shaft is rocked and by the breaking of which the shaft is returned to normal position (Figs. 27, 28). 110 192 is a pin carried by an arm 193 (Figs. 6, 18 and 19) fixed on the main cam shaft at the left of the machine. Said pin at this time engages the hook 194 of a link 195, (Figs. 27, 28), and pulls the link forward. The link is pivoted at 196 to the lower arm 197 of 115 an angle lever having an upper arm 198 and mounted on the frame by a pivot 199. The link is also connected with the said arm 197 by a spring 200 tending to pull the link upward, such action being limited by a stop 120 130

201 on the link and engaging the front of the arm. The rearward movement of the arm is limited by a stop pin 202 on the frame Fig. 6, and after the arm 197 has been pulled forward by the link 195, from the position shown in Fig. 6 to that shown in Fig. 27, it bears against a pin 203 on an arm 204 of the rock shaft 120, the arm being pulled rearward by a spring 205. The action of the 10 link rocks the upper arm 198 rearward causing it to press on a short lateral lug 206 of an arm 207 mounted on the said pivot 199, and to rock the arm 207 rearward. The latter arm is connected by a toggle 208 with 15 an arm 209 fixed on the rock shaft 131, whereby the latter is rocked forward to release the dog pawls (Figs. 25, 26). The toggle members are controlled by a spring 208' Fig. 29^a and are arrested in extended and 20 locked position by a tooth 210 on one member which engages a corresponding tooth 211 on the arm 207. One of the toggle members is formed with an arm 212 adapted to encounter (on the said rearward movement) a 25 fixed stop pin 213 on the frame Fig. 27, whereby the middle toggle pivot is thrown upward enough to break the toggle and allow the parts to assume the positions shown in Fig. 28. This allows the rock shaft 131 to 30 rock backward and release the dog pawls (Fig. 22), said rocking being arrested by an arm 214 on the shaft, which encounters the pin 213 (Fig. 28). 215 is a two-armed latch pivoted loosely on the rock shaft and controlled by a spring 216 (Figs. 27, 29^a). At 35 this time the latch drops over the upper end of the arm 198 and holds it in rearward position (Fig. 28) while the pin 192 rocks rearward. The forward swinging of the arm 40 197 under the pull of the link 195 has changed the angle between it and the link 195 and separated the stop 201 from the arm, and as the pin 192 moves back from over the hook 194 the spring 200 pulls the link up out 45 of the path of the pin. 217 is an arm on the transfer shaft 218 which bears against the rear arm of the latch 215, and when this shaft rocks forward it throws up the latch and allows the parts to return to the position 50 shown in Fig. 27 (excepting that the arm 197 will be against the pin 202).

Second, the rock shaft 120 is turned rearward to release the setting pawls 116. This is accomplished by the said pin 203 and lever 55 arm 197 (Figs. 25, 27). Immediately after the two parts of the multiplying levers have been locked together by the dogs the lower arm 197 of the lever turns forward and actuates the pin 203 on the arm 204. This overcomes the tension of the shaft returning 60 spring 205 and rocks the shaft rearwardly enough to engage the tails of the pawls 116 (Fig. 25) and release the pawls (Fig. 29).

Multiple control mechanism, (Figs. 31 to 65 39.)—This automatically determines the

number of additive strokes which shall be made for each digit of the multiplier, which may be from one to nine. It comprises several orders (according to the capacity of the machine) of oscillating parts, including 70 numeral wheel indicators 219, working by eleven stepped positions. The first nine steps between these positions, that is to say, from 9 to 0, are additive; the next step from 0 to blank or normal is adjustive in preparation for the automatic operation of the next lower order of control mechanism. Each indicator wheel has its periphery divided into eleven spaces showing in order, as it rotates step by step forward, 9, 8, 7, 6, 5, 80 4, 3, 2, 1, 0 and a blank space (Fig. 31). The principle of operation is to set each of the several orders of control mechanism which are desired to operate, back a certain number of these steps, according to the digits of 85 the multiplier. Thus, if the multiplier be 123 that indicator wheel 219 which is in line with the units order of the multiplicand is set to 1 (to represent the hundreds order of the multiplier), the next lower wheel is set 90 to 2 and the next lower wheel is set to 3. If the multiplicand has not too many places any three successive controls may be thus set. If they are set as first stated it will be known whether a showing of the entire product is within the capacity of the adding machine numeral wheels. If, after setting the control to 1 (for the example supposed), in line with the units order of the multiplicand it is found that there are not two controls 100 left to the right which can be set to 2 and 3, then the entire product is not within the capacity of the adding numeral wheels. In such case any three successive control indicators can be set to show 123, and the 105 product will be approximate, the right hand figures beyond the capacity of the machine (which are often negligible, as in astronomical and other estimates dealing in large numbers), not appearing on the adding 110 wheels while the necessary part of the calculation is conserved. In many cases this will be practically sufficient, just as low decimals below two places are often neglected. Then, after being so set, the orders of control mechanism, one after the other beginning with 115 the highest, are caused by the power mechanism to return step by step to their normal positions, an additive stroke of the multiplying levers being made for each step and 120 such return, excepting for the step from 0 to blank. Such setting and return of the control mechanisms are regulated primarily by eleven-tooth ratchets and suitable pawls. The indicator wheels 219 are mounted to 125 turn on a cross pivot rod 220 held in the frame, and they are covered by a removable plate 221 provided with an aperture 222 for each wheel so arranged that when the wheel is in normal position the blank space 130

- shows through the aperture, and when the wheel is turned back to multiply for any digit such digit will show through the aperture.
- 5 Each order of the control mechanism (with exceptions as to the highest and lowest orders, hereafter noted) is further provided with the following parts: a series of setting keys 228 marked from 9 to 0, each 10 having in setting function a multiplier digit value corresponding with its marking, each key being mounted to slide radially inward and outward in the plate 221, and spring pressed outward; and having a foot 224 15 which when the key is depressed, releases the control mechanism of its order and acts as a stop (Fig. 33) to arrest the same in position to thereafter cause as many multiplying strokes as there are units in the marking of 20 the key; a left hand toothed pinion 225 and ratchet 226 and a right hand pinion 227 and ratchet 228, all attached to the indicator wheel 219 and turning therewith on said pivot rod 220; a toothed segment 229 pivotally mounted by an arm 230 on the rod 220; a driving pawl 231 pivoted at 232 on said segment and pressed toward the ratchet 226 by a spring 233 which encircles its pivot; a toothed segment 234 mounted to oscillate 25 on the cross pivot rod 156, meshing with the segment 229 and acting to reciprocate the pawl to give a step by step movement to the indicator wheel and other connected parts of the control mechanism, and formed 30 with a cam arm 235, a driving arm 236 and a limiting jaw 237 which acts as a stop on a frame tie rod; an arm 238 pivoted on the rod 156, arranged to be stopped by a frame tie rod 3 having a flange 239 engaging above 35 a lateral lip 240 on the pawl whereby the pawl may be held away from the ratchet 226; a lever mounted on the cross rod 156 having an arm 241 which is constantly pressed upward by a spring 242 attached at 40 its upper end to the frame, an arm 243 adapted to be encountered and rocked backward by a pin 244 on the externally toothed sector of the next higher order of control mechanism when or as said order is or arrives at neutral or blank position, and a 45 forward arm 245 having a pin 246 which passes through a slot 247 in the arm 238; a spring 248 which connects said pin with the arm 238 and by which the latter may be 50 raised to allow of the engagement of the pawl; a driving roll 249 engaging a slot 250 in the arm 236 and fixed on a slotted arm 251 loose on the main rock shaft 100; a driving arm 252 keyed to the shaft and having a hub 253 on which the slotted arm is mounted, and having a pin 254 which enters the slotted arm to rock the latter for about 18° during the last part of the forward and rearward rock of the main shaft; 55 a three armed pawl cut out lever 255 which

is pulled backward on its fixed pivot 256 by a spring 257 and is arrested by a lip 258 which encounters a part of the main frame (as in Fig. 34); a projection 259 on the side of the segment 234; a pivoted stop 260 on a pin 261 fixed in the arm 238 which is pressed forward against a stop pin 262 by a spring 263 encircling the pivot pin, this pivoted stop being adapted to be pressed down by the said projection 259 when in line with the latter (Fig. 39) and to be held down by an arm of the cut out lever 255 when in line with the same (Figs. 34, 35); preferably also an arm 264 on a fixed pivot, pressed by a spring 265 and having a friction roll 266 which enters one or the other of notches 267 on the slotted arm to keep the latter and connected parts in either forward or rearward position during the intermediate period of movement of the pin 254; an externally toothed sector 268 mounted to oscillate forward, and backward step by step, on the rod 156, meshing with and actuated by the right hand pinion 227 and having a stop arm 269 adapted to be arrested by the key foot 224 (Fig. 33); the said pin 244 arranged to push rearward the arm 243 of the next lower order when said pin (Fig. 34) is at the 0 position; a V-pin 270 (Figs. 56, 58, 60, 62) arranged to hold down notched fingers 271 and 272 until the pin comes over the notches 389, 418; a latch 273 pivoted at 274 and adapted to be depressed by a rock shaft arm 275 (Figs. 44, 45), the said latch being pressed by a spring 276 toward a stop pin 277 fixed in the sector, and being formed with a latch hook 278 arranged to hook under the lip 279 of a pivoted pushing arm 280 and hold the latter in inoperative position; the said pushing arm 280 pivoted at 281 on the sector, normally pressed down toward operative position by a spring 282, formed with the said lip 279 and a rear pushing end 283 and having a lateral roll 284 by which it may be raised by the cam arm 235 so as to be held by the latch 273; an arm 285 being one of a series of such arms fixed on the cross rock shaft 286, by which the shaft is turned rearward when the pushing arm 280 acts on the arm 285; an internally toothed sector 287 mounted to oscillate backward, and forward step by step, meshing with and actuated by the left hand pinion 225 and having a spring 288 which presses it and the pinions and ratchets 289 backward and the externally toothed sector forward, a pin 289 on its left side arranged to bear downward on an arm of the cut out lever 255 and turn the same forward when the pin is passing from 0 position to normal or blank position; a V-pin 290 arranged to hold in rearward position notched fingers 291 (Figs. 40, 4 and 62) until the pin comes opposite to their notches, and a pin 292 engaging a slot in a return slide 293 (Fig. 35); 130

the said return slide 293 which is formed with the said slot 294 and a rear handle 295 by which the control mechanism of an order can be pushed forward to 0 position, the 5 said slot allowing the mechanism to thereafter automatically move one step more to normal position, the said slide being contained and guided in a slot 296 in the under side of the plate 221 and the said handle being exterior to the plate; an arm 297, being one of a series of such arms fixed on the cross rock shaft 298 and arranged, when in 10 normal position, to engage and arrest the cut out levers 255 by its said arms, a back stop pawl 299 (Fig. 33) arranged over the right hand ratchet 228 to hold each step of forward movement which the indicator wheel and connected parts receive from the driving pawl 226, said back stop pawl being pivoted to a frame part at 300, being 15 pressed toward its ratchet by a spring 301 and having a tail 302; and an equalizing bar 303, which is pressed outward by the pawl spring and tail against the key feet 224 and is mounted on parallel equalizing links 304 which give it a parallel motion when it is pressed inward by any key foot to release the pawl.

Some of the above mentioned parts are not 20 necessary in the highest order, and others are unnecessary in the lowest order; thus in the highest order the parts 235, 241, 242, 243 and 245 would be without function and may be omitted, there being no parts of a superior order to coöperate with them to automatically transmit a control actuation, and the spring 248 is attached to a pin fixed in the frame. So in the lowest order the latch 273, pushing stop 280 and pin 244 are 25 unnecessary and are omitted, there being no lower order to be set in operation, and the right hand finger of the pair of fingers 291 is omitted for the same reason.

Suppose that a control is to be set to 30 multiply by 3; the 3 indicator key is depressed (Fig. 33), the key foot depresses the equalizing bar 303, the back stop pawl 299 is released, the spring 288 is allowed to exert its pull on the internally toothed sector (Fig. 32), the two pinions, the two ratchets and the indicator wheel are turned backward and the externally toothed sector is turned forward until its stop arm 269 encounters the key foot, and the indicator 35 wheel shows 3 through the aperture 222. The key is now released by the finger and springs outward, allowing the back stop pawl to engage its ratchet and hold the said position of the parts for the time being. 40 In the same manner all other keys and orders of control mechanism representing the multiplier are set.

The machine would now be ready for operation if it were not for the locking of certain parts to guard against mismanipula-

tion, the various locks being controlled by the locking key 171. The description of said locks can best be understood later, and the description of the multiple control mechanism is continued under the assumption 70 that the locking key is now depressed and the locks released.

Beginning now to actuate the power shaft of the machine by the crank 173, the main cam shaft is caused to rock, first 18.5° forward and then backward and forward as above described. The slotted arm 251 (Fig. 34) is thereby given by the pin arm 252 a forward and backward oscillation of 18.5°, which, through the toothed segments, works 80 the driving pawl backward and forward. This pawl is in engagement with its ratchet because the depression of the locking key (Fig. 36) has allowed the rock shaft 298 to turn rearward, removing the arm 297 from 85 under the rear arm of the cut out lever 255 so that the middle arm of said lever will spring forward from over the pivoted stop 260 to release the pawl controlling arm 238 (Figs. 35, 37). The cut out lever can thus 90 move because the pin 289 on the internally toothed sector has been removed from against the lever arm (Figs. 34, 35) by the supposed setting at 3. Also the pawl controlling arm can move up because the pin 95 244 on the externally toothed sector in the next higher order, being unset, is at normal and when at normal it bears rearward against the arm 243 causing the pin 246 to occupy the upper end of its slot (Fig. 34) 100 whereby the spring 248 can now pull the arm 238 up (Fig. 38). The reciprocation of the driving pawl now gives a step by step forward rotation to the two ratchets and pinions and attached indicator wheel, 105 and turns the latter first from 3 to 2 (in the case of the supposed setting at 3), then to 1, then to 0 and finally to normal or blank. When in the above operation, the control arrives at 0 three steps and three 110 additions of the multiplicand have been made, and no more such additions are to be made of the multiplicand in its present setting on the adding mechanism, but it is to be trans-set one place to the right before 115 its repetitions by the next lower stroke control begin. Such shifting or trans-setting is performed by the trans-setting mechanism hereafter described. But it is first necessary that the mechanism of the higher 120 control refrain from causing any addition during the remaining step from 0 to normal. This is insured by the cipher control mechanism, the operation of which is more or less coincident with the operation of the trans-setting mechanism. As this control makes its last step from 0 to normal the pin 289 on the internally toothed sector engages the pawl cut out lever 255 and causes it to force 125 back the pivoted stop 260 under the pro- 130

jection 259 of the toothed segment while the latter is elevated (Fig. 39). The down stroke of the segment therefore causes the said projection to force the pivoted stop 5 and the pawl controlling arm 238 downward, throwing the pawl out of its ratchet and leaving this control mechanism inoperative. Thereupon the pivoted stop springs forward under the arm of the cut out lever 10 255 and so remains (Fig. 34) during the following operation of the machine and until a new example be set up. The operation of the toothed segments will continue but the reciprocation of the pawl will be inoperative.

In thus arriving at normal the pin 244, of the control whose operation has just been described, bears against the arm 243 in the next lower control, and causes its pawl to 20 engage and the said lower control to be immediately started in a similar operation, for a number of steps according to its setting.

The multiple stroke controls are not actuated one by another in the preferred form 25 of the machine. A higher control will bring parts to such position that the operation of a lower control may be caused to begin, but the actual operation of the control is from the power mechanism, separately by each 30 control. The number of multiple controls can therefore be readily increased to enlarge the capacity of the machine. Seven controls are illustrated as sufficient for an explanation of the invention, and in this machine another control mechanism could be mounted in the existing space at the left of the seventh control (Fig. 11).

When the highest set order of multiple control has caused all of the multiplying 40 strokes due to its setting, and arrives at 0 position, its latch 273 is immediately under the arm 275 of the constantly rocking shaft 305, and said arm descends on the latch, now in the path of the arm, and its lateral 45 pin 306 depresses the latter. (Fig. 44). The shaft 305 is so rocked (Figs. 42, 43), at the last part of each rearward rock of the main cam shaft at each stroke of each of the successively acting controls, by an arm 307 50 fixed on the main shaft and having a pin 308 which enters the slotted arm 309. The latter carries a roll 310 entering a radial slot 311 in an arm 312, the latter being pivoted on the cross rod 156 and controlled 55 by a spring 313. The said arm 312 is connected with a forward arm 314 of the rock shaft by a link 315. When the latch 273 is so depressed its hook releases the pushing arm 280 which springs down (Fig. 44) into 60 line with the arm 285 fixed on the rock shaft 286, which is pressed by a spring 316 and limited in rocking by an arm 317 and stop pin 318 on the frame (Fig. 48). The next rearward step of the externally toothed 65 segment from 0 to normal rocks the arm

and shaft rearward to permit the trans-setting operation.

Cipher control mechanism (Figs. 40, 41.)—This mechanism prevents accumulation for any factor-cipher and is controlled 70 by the corresponding factor-setting device. The vertical notched control fingers 291 are arranged in pairs (excepting in the highest order) the second or right hand finger of a higher order being integral and movable 75 with the first or left hand finger of the next lower order (Figs. 60, 62), each pair of fingers being pivotally mounted on a cross pivot rod 319 held in the frame and being pulled forward by a spring 320. The higher 80 or left hand finger of each pair has its notch 321 so arranged that the V-pin 290 of the internally toothed sector of the next higher order will come directly in front of the said notch when the control mechanism 85 of such higher order reaches the normal or last position, which is the blank position of its indicator wheel, and the notch 322 of the right hand or second finger is so arranged that the V-pin of its own order will come 90 in front of it when the latter mechanism reaches the 0 position and its indicator wheel registers. When such combination of controls (or control positions) occurs the them active (highest) control, which is the 95 lower of the two orders above referred to, should allow no further multiplication during the step from 0 to normal or until the multiplicand has been trans-set to the right. Accordingly at this time the said pair of 100 fingers, the right hand one of which is in the order which has arrived at 0, is allowed to move forward under the pull of its spring 320, because both of the otherwise opposing V-pins are in front of the said notches. 105 Connected with each pair of fingers is a trip mechanism adapted to separate the column actuator links from the multiplying levers. 251 is the slotted arm which actuates the driving pawl 231 as already described and 110 which is constantly rocked backward and forward during the last part of each rock of the main shaft. It is formed with a tooth 328. 324 is one of a series of arms, 115 one for each order of control mechanism, fixed on the rock shaft 325 and extending over in front of the main rock shaft; and having pivoted at its front end a pawl 326 adapted to be swung rearward over the tooth 323 by the notched fingers (Figs. 40 120 and 4). The upper arm of the pawl is slotted at 327 and such slot is engaged by a pin 328 fixed in a rearward arm of the notched fingers 291. 329 is one of two arms (one at each side of the machine) fixed on 125 the rock shaft 325 and having pivoted to its lower end a forwardly extending link 330. The front end of the link is slotted at 331 and the slot embraces a pin 332 fixed in an arm 333 which extends down from the rock 130

shaft 145. The slot 327 allows the pawl to work up and down on the pin 328 as may be required. The construction is such that when the fingers 291 move forward the pawl 326 is thrown over the tooth 323 and the following backward rock of the slotted link 251 causes the arm 324 and shaft 325 to be rocked upward and backward and the arms 329 to be rocked forward, which, through the links 330, throws all of the column actuator links 139 out of engagement with the multiplying levers and prevents for the moment any adding action in any order. The slot 321 allows of the said links being thrown out at other times and by other means. The links 139 are thus disengaged and accumulation stopped just after the lower of the controls comprising the said notched fingers 291 has arrived at the 0 position. This preventing of addition occurs near the end of the operation of the highest working control and just before the next lower control takes up the controlling function. It is necessary however to reconnect the links 139 before the first additive stroke of the next lower control (after trans-setting the multiplicand) begins. 334 is an arm fixed on the rock shaft 325 and having at its lower end a tooth 335 which is normally engaged by a corresponding tooth 336 of a detent lever 337 pivoted on the column actuator pivot rod 51, having its rear arm engaged with the rear side of a swingable bar 338 and controlled by a spring 339 so as to pull the front arm of the detent lever upward and its rear arm forward against the bar 338. The teeth 335 and 336 thus engage when the arm 334 is in its normal rear position and the accumulating links are not disconnected (Fig. 40). When the arm is caused to be thrown forward by the notched fingers 291 the said teeth are disengaged and the tooth of the detent lever springs up to abut the rear side of the arm 334 (Fig. 41) so as to maintain the disconnection of the links 139 while the step of the active control from 0 to normal, causes the V-pin to pass below its notch, the notched fingers to be forced rearward and the pawl 326 to be thrown out of the tooth 323. The bar 338 extends transversely of the machine and is carried at each end by an arm 340 pivoted to the cross rod 51. At the right side of the machine the arm 340 is continued forward in the form of an arm 341 which is connected by a link 342 with a horizontal arm 343 pivoted at 344 to the frame. This arm has fixed to its inner side a pin or projection 346 which is engaged by a notch 347 of another arm 348 also mounted on the pivot 344. 339 is the spring (Figs. 40 and 8) by which the bar 338 is pulled forward, which also presses the pin 346 against its notch 347 and presses the arm 348 upward and rearward. 349 is a two arm lever ex-

tending upward and downward from the trans-setting rock shaft 218 to which it is fixed. The upper arm is connected by a two link toggle 350 with the end of the arm 348. The toggle is arrested in extended 70 position by a tooth 351 on one toggle link which engages a tooth 352 on the arm 349, and one of the toggle links has an arm 353 arranged to encounter a fixed stop pin 354 when the trans-setting shaft has rocked far 75 enough forward, whereby the toggle will be broken and the arm 348 and spring 339 relieved of the forward pressure of the arm 349. 355 is a light spring which acts to straighten the toggle when the arm 349 80 moves rearward. The construction is such that when the trans-setting shaft 218 rocks forward (which occurs when the active control has reached normal position and can no longer cause an accumulating stroke) the 85 arm 349 forces the toggle forward and downward, causing the bar 338 to swing outward and the tooth 336 to be depressed against the pull of the spring 356; whereupon the arm 334 is released and is forced 90 back by the spring 357, acting through the links 330, so that the teeth 335 and 336 re-engage in normal position (Fig. 40).

The above operation is caused by the notched fingers 291 whenever the active 95 (highest) control reaches the 0 position, because the next higher control is then at the normal position either because it was not set or because it has finished its cycle. It also occurs when the next lower control be- 100 comes active at the 0 position, having been originally so set. If the original setting of the multiplier were 3000003 and the multiplicand 999 (which on a machine of the capacity illustrated have as many places as 105 possible if the full product is to appear on the adding wheels), the highest control would cause 999 to be repeated three times at the left, then the 999 would be rapidly trans-set to the right six times without an additive stroke, and then 999 would be repeated three times at the right, giving a product of 2997002997. It will be noted from the foregoing that controls are always to be set at 0 (and not left unset) to represent 110 all intermediate ciphers in the multiplier. Ciphers terminating the multiplier need not be set up. Ciphers at the left of the multiplier, as in multiplying by .0024, must not be set up because the setting of the adding 115 keys has begun an accumulation of 24 which the cipher control does not prevent.

The column trans-setting mechanism, (Figs. 42 to 54.)—The term “trans-setting” is herein employed to signify that the setting 120 that has been given to mechanism in one ordinal place in the machine is thereafter derived from that ordinal place and given over to mechanism in another ordinal place, to similarly delimit the action of the latter. 125

And in the preferred embodiment of the invention, such trans-setting means is independent of the primary setting means and is also automatically operated without manual intervention. When the multiple control mechanism of the highest order which has been set has finished all of its multiplying strokes its indicator wheel will show blank, and all of the multiplying levers will be at the bottom of their strokes, against the stop bar 106. The dogs 109 will or may be at various heights above the stop bar, according to the various digits of the multiplicand and the corresponding setting of the dog levers. At this time all of the dogs will be situated radially within arc bars 358 (Figs. 49, 50) which are pivoted at 359 to the lower ends of equalizing parallel arms 360 pivoted on cross rods 361 held in the frame. There is an arc bar for each dog and it is formed on its inner face with ten notches 362 to correspond with the possible ten positions of any dog. The arc of the inner notched face of the bar is concentric with the lever pivot 101. Each bar is formed with a short downwardly and rearwardly extending slot 363 in which works a flanged roll 364. Each roll is pivoted at 365 to the left side of an arm 366 all of which arms are fixed on the transverse trans-setting and neutralizing rock shaft 218 mounted in the frame. When the parts are in the last described position the shaft 218 is rocked forward sufficiently to cause all of the arc bars to engage their respective dogs, and force the latter inward against the tensions of their springs until the dogs are each released from their inner racks 103, and pass the neutral point, and engage by their outer teeth 126 the outer rack 104 of the rack lever in the next lower order to the right; whereupon the dog pawls 128 each engages its outer tooth 127. Thus each rack lever which was originally set is for the time being freed from its own dog lever and is locked and is moved for one upward stroke with and by the next higher dog lever. The highest (leftmost) rack lever has finished its multiplying functions and is left resting on the stop bar, locked at the neutral or inoperative position, by means of its neutral notch 135, with the next higher dog lever. The main cam shaft now elevates all of the dog levers, each carrying with it the right hand rack lever with the same additive setting which the rack lever formerly had on its own dog lever. While the dog levers are returning to their highest point the first accumulation of the new setting occurs, and after they have reached said highest point they are all in line across the machine; and at this time the shaft 131 is rocked to depress the tails of the dog pawls 128. This releases each dog and they spring outward into engagement with the

inner racks 103 of their own rack levers, the latter having at the instant the new settings just described, whereby said new setting is preserved during the next cycle of the multiple control mechanism. Thus each multiplying lever has now the additive setting which the lever next to the left of it formerly had, and each digit of the entire multiplicand is trans-set to a denomination one place lower than it formerly had, in which new denominations it is now repeated as many times as there are units in the second (from the left) figure of the multiplier. It will be understood that such trans-setting drops out of operation the highest column actuator 8 which was formerly driven, and brings into operation a new column actuator to the right, each active column actuator now adding the same amount as the next higher column actuator added in the first cycle of operation. Similar cycles of operation are repeated, according to the denominations of the multiplier, until the latter is exhausted and the indicator wheels of the multiple control mechanism all show blanks. In the trans-setting of a cipher of the multiplicand the multiplying lever for which has no movement, the outer dog tooth enters the outer neutral notch 135.

When the lowest newly set rack lever, having been inactive, is thus set by its arc bar 358 it is at the moment resting on the stop bar 106 in its lowest position. It gets its proper setting because, although it is not raised as in an original setting, the left hand dog lever is at the moment depressed just the proper distance to give to the right hand rack lever the same additive stroke as its own left hand rack lever had. It is now raised for one upward stroke by this left hand dog lever, its own dog lever remaining in neutral position, whereby when the dog pawl is tripped and the dog springs outward this rack will be locked to its own dog lever with the same proper additive throw (to and from the stop bar) as if it had been set up by the depression of a key as in its original setting.

The trans-setting rock shaft 218 is rocked forward as above described after the active control has reached the normal or last position. This is preferably accomplished by the following means: The lower arm 367 which is fixed on the left hand end of this rock shaft is constantly pressed forward by a spring 368 (Fig. 48), the rearward turning of the shaft, however, being limited by a stop arm 369 which rests against the rear side of the stop bar 106. Engaging the front side of the arm 367 is the inwardly bent lip 370 of a lever 371 (Fig. 47), which is pivoted on a bearing of the shaft 218 (Fig. 47^a) and is limited as to rearward turning by the fixed stop pin 213. Pivoted at 372 on the arm 371 is an angle lever con-

stituting a trans-setting link 373 and arm 374. A lip 375 of this link is bent out and around an arc-shaped extension of the arm 371 to keep the parts together as they turn 5 relative to each other. A spring 376 acts to pull the link 373 rearward and the arm 374 downward. The link is formed with a hook 377 by which the link may be pulled downward by a pin 378 when the hook is 10 caused to move rearward under the pin. The pin is fixed on a plate 379 which turns loosely on the bearing of the main shaft. At the outer side of the plate 379 is the cam and hook plate 193 fixed on the main shaft so as 15 to constantly rock therewith and formed with an internal cam 380 and a downwardly turned hook 381. The link 373 has fixed thereon a roll 382 which extends into the cam opening of the plate 193, the rear part 20 of the cam being shaped to let the hook swing rearwardly under the pin 378 and the front part of the cam being adapted to draw the roll 382 toward the center and to remove the link hook forward from under the pin. 25 The plate 379 is pressed so as to yieldingly elevate the pin 378 by a spring 383, and such tendency is limited by a fixed pin 384 which arrests an arm of the plate. The arm 374 of the link extends forward and upward and is 30 formed with a front inwardly turned lip 385 and a rear lip 386. The arm 387 attached to the rock shaft 286 is normally under the forward lip 385 to prevent the hook 377 from swinging rearward even if 35 the cam 380 would allow it to do so. This arm 387 is turned rearward to release the link arm after the active control has reached normal position, by the pushing stop 280 as already explained. The construction is such 40 that after a control has finished its additive steps, the latch 273 has been depressed and the pushing stop 280 has rocked the shaft 286 rearward, the link arm 374 is thereby released by the arm 387 and is pulled down 45 by the spring 376 (Fig. 47), so that the hook 377 moves rearward under the pin 378. At this moment the hook arm 193 rocks downward engaging the pin 378 and forcing it down on the trans-setting hook 377. There- 50 by the arm 371 is pulled down and the lip 370 caused to force back the lower arm 367 of the trans-setting shaft, which forces the arc bars and trans-setting dogs fully inward, as already described. During this 55 movement the cam arm 235 is rocked forward by the movement of its segment 234, thereby lifting the pushing arm 280 until it is latched by the hook 278 in normal position. The end of the cam arm which thus 60 restores the said arm is under the roll 284 only when the latter is at normal or final position.

Column trans-setting lock, (Figs. 55, 56.)—When the lowest set control has 65 reached the normal position the example is

finished, and it is desired to bring the whole machine to normal position. This includes bringing the dogs 109 to neutral position so that they do not lock any rack lever. This is done by an operation quite similar to the 70 trans-setting operation. Before this is performed, however, the trans-setting mechanism (or the primary actuating portion of it) is locked so that the dogs will be forced only partly and not fully inward. The said 75 notched fingers 271 are shown in plan view in Fig. 55 with the V-pins 270 above them in the position when all of the multiple controls to the left have arrived at normal and one right hand control is still at 0. In this 80 position the trans-setting lock shaft 388 which carries the said fingers has rocked backward, because the notches 389 are long enough to accommodate the V-pins in both the 0 and in the (further rearward) normal 85 positions. Therefore all of the V-pins have notches beneath them and they can rise and allow the shaft to turn under the pull of the spring 390 attached to the arm 419 fixed on the shaft. 391 is a latch fixed on the shaft 90 and adapted to be hooked under the rear lip 386 of the trans-setting link arm, though out of engagement therewith except at this time. The said rocking of the shaft now throws the latch forward under the said lip (Fig. 95 56) and holds the trans-setting link out of operation, so that the trans-setting shaft cannot be moved thereby.

It may here be stated that this lock is not essential to the operation of the machine, 100 but is an advantageous safety lock against manipulation. If the multiplier be always set on the right hand controls (leaving no unset control to the right) there would be no trans-setting at the end of the multiplication by the last control, because there is no latch 273 in this last order of control to start the trans-setting mechanism in operation, even in the absence of the latch 391. But new or careless operators would not 105 observe such precision in the setting of the controls, and the said locking mechanism will prevent trans-setting, as described, and allow controls to the left to be set, with controls to the right remaining unset, an accurate result to be obtained, and the machine left restored to normal position in all respects.

Neutralizing mechanism, (Figs. 57 to 59.)—It is the object of this mechanism to 120 restore parts of the machine, especially the multiplying levers, to normal positions, leaving the said levers with their two parts unlocked by the dogs and separate just as they were when the above described multiplying 125 operation was first begun. This is accomplished by a trans-setting shaft operating mechanism, which, in this instance, is arranged at the right side of the machine. It operates to force the dogs inward, in a gen- 130

eral way, similarly to the trans-setting mechanism (Figs. 46, 47) already described and which is arranged at the left side of the machine. These said arrangements might be 5 reversed, but as the trans-setting occurs more frequently than the neutralizing and puts more load on the power mechanism the arrangement shown is preferred, thereby locating the trans-setting actuator at the same 10 end of the main cam shaft that receives actuation from the power shaft. Referring principally to Figs. 3, 58 and 59, the latter of which show mechanism at the right of the machine viewed from the left, 392 is a 15 plate fixed on the main shaft and formed with an internal cam 393 and hook 394. 395 is an arm mounted loosely on the hub of said plate, having a pin 396 fixed in its outer face, pulled rearward by a spring 397 and 20 arrested by a fixed stop pin 398. 399 is a neutralizing link having an arm 400 mounted on a movable pivot 401 and pulled rearward by a spring 402. The arm is formed with a lateral lip 403 and the link has mounted 25 on its lower end a roll 404 arranged on the cam 393. 405 is an arm mounted loosely on a bearing or other fixed pivot of the frame and carrying the said pivot 401 of the neutralizing link. It is extended forward 30 of the pivot in the form of a segment arm 406 which movably confines the link by a bent-over lip 407. It also has a stop arm 408 which abuts against the fixed stop pin 354, against which it is pulled by the effect 35 of the spring 402, and a lip 409 bearing rearwardly against the lower arm of the lever 349 which is fixed on the trans-setting shaft 218. 410 is a latch formed of two members pivoted together and to the frame 40 on the pivot 411 of the shaft 305. Its lower member is hooked and adapted to sustain the lip 403 and the neutralizing link excepting when the neutralizing is to be performed. The two members of the latch are connected 45 by a spring 412 which presses the hooked member forward for a limited distance relative to the rear member, so that if the hooked member is in latching position when the lip 403 is below it and the lip be elevated by the action of the cam 393, the lip 50 will pass above the yielding hook member and be locked up. The rear latch member has a pin 413 which enters a slot in an arm 414, the latter being fixed on the neutralizing rock shaft 415. The latter extends 55 across the orders of control mechanism, carrying the said neutralizing fingers 272, one in each order, and is pulled by an arm 416 and spring 417 so as to tend to rock backward. The said fingers have notches 418 on their upper edges, over which the V-pins 270 of the externally toothed sectors arrive when they reach the normal position.

The construction is such that when the 60 last control reaches normal position the V-

pin of each control has a notch 418 (Figs. 58 and 62) under it (Fig. 57). Consequently the fingers 272 can rise, allowing the shaft 415 to rock backward, which causes the latch 410 to release the neutralizing link 70 (Fig. 58). The hook 420 of the latter is thereupon allowed by the cam 393, when it turns downward and forward, to swing back under the pin 396, which latter is immediately depressed by the hook 394. This 75 rocks the trans-setting shaft 415 forward and causes the arc bars to force the dogs inward to neutral position, not engaging either the inner or outer racks of the rack levers. The dogs are thus forced not fully inward 80 but only to the neutral position because the neutralizing link is a little longer than the trans-setting link and does not give so much rock to the trans-setting shaft. While the neutralizing of the multiplying levers is thus 85 being performed the trans-setting link 373, which would otherwise operate, is held out of action by the latch 391 as previously explained. After the neutralizing link has completed its downward movement the hook 90 394 returns upward with the rock shaft and releases the link, and the latter is raised by the spring 402 and is latched above the latch 410, and so remains till the termination of a new problem. After this the power shaft 95 makes its final turn of about half a revolution, the locking key 171 springs up and the machine comes to rest with all of the parts in normal position, and the product or other result shown on the adding numeral wheels. 100

Resetting and safety locking mechanism, (Figs. 60 to 64.)—Most of this mechanism is connected with the said locking key 171 so that various locks are effected by the depression of the key, which remains depressed 105 and reciprocally cannot itself be released until all of the mechanical movements necessary to the problem to be performed have been fulfilled, whereupon said key is automatically released. 421 is a link pivoted at 110 422 to the main locking pawl 190 of the power shaft and pivoted at 423 to a lever 424, the latter being pivoted at 425 to the main frame. This lever is loosely connected by a pin 426 and slot 427 with another 115 lever 428 which is pivotally mounted at 429 on the frame and has a lower arm 430 formed with the said slot 427 and an upper arm 431 on the inner face of which is fixed a pin or roll 432. This roll is arranged in 120 the cam slot 433 formed in the locking lever 434, which is pivoted to the main frame at 156, is pulled upward by a spring 435, and has fixed to its front end an arm 436 which extends through a vertical slot 437 in the 125 casing and carries at its outer end the said locking key 171. The construction, and the shape of this said cam slot 433, are such that if the key be in its elevated position, which it occupies normally unless an example is 130

being performed, and which is shown in Fig. 63, the lower arm 430, the lever 424 and the link 421 will be forced forward, thereby locking the pawl 190 against the 5 rear face of the projection 189 on the power shaft, and if the locking key be pressed down the power mechanism is freed for operation, by reason of the lifting of the pawl by the said connections. 438 is a latch pivoted at 439 to the frame, having its rear end pressed down by a spring 440 so as to rest on a pin 441 fixed on the slotted cam of the canceling shaft. This latch is formed with a shoulder 442, and the arm 430 has an outwardly bent lip 443 adapted to engage with said shoulder when the pin 441 is depressed by the actuation of the canceling handle 53. 444 is a horizontal shoulder formed on the said arm 430 and adapted to engage beneath another pin 445 fixed on the slotted canceling cam. The arrangement is such that when the locking key is elevated the canceling handle can be turned and a canceling or zeroizing of the adding machine performed, and if the adding keys have been erroneously set in connection with the multiplying levers, and the locking key not yet depressed, the machine may be cleared by the usual operation of the canceling handle, with which coöperates the key set clearing device (Figs. 65, 66), hereafter explained. But as soon as such canceling movement begins the depression of the pin 441 allows the shoulder 442 to engage behind the lip 443, thereby locking the arms 430 and 431 and preventing the locking lever 434 (by reason of the shape of the slot 433) from being depressed until the canceling mechanism is returned to normal position. 40 When the locking key is depressed the shoulder 444 engages beneath the pin 445 and prevents the operation of the canceling mechanism. Any interference of the multiplying mechanism with the canceling mechanism, 45 in respect of their actions on the column actuators, is thus prohibited.

The locking key and lever are also held from depression when the handle 134 is set at Add. 446 is a horizontal lever (see also Figs. 15 to 17) pivoted at 447 to the frame and having at its rear end an up-turned stop 448 adapted to be elevated behind the pivot 423 so as to hold the levers 424 and 428 from turning, in which case the slot 433 will hold 55 the locking lever from being depressed. Also, when it is depressed the pivot 423 will be over the stop 448 and hold the rear end of the lever 446 from rising. 449 is a lip formed on the lever 446 and arranged to 60 rest on the rear side of the rock shaft 450, the rear end of the lever 446 tending to fall by gravity. When the handle 134 is set at Add the links 139 are disconnected and the multiplying lever arms 114 cannot be depressed. 65 These arms have mounted on them rolls 451 (Figs. 15, 22) adapted, on the depression of the arms, to rock forward the cam arms 452 with which the rolls engage. These arms are fixed on the shaft 450. Consequently the shaft cannot be caused to rock 70 rearward to release the lip 449, the stop 448 remains behind the pivot 423 and the lock lever 434 is maintained elevated. The shaft 450 has fixed thereon an arm 450' formed with an outwardly turned lip 450' adapted 75 to lock in front of a lug 146' on the angle lever 146 when the machine is set at Mul. and the shaft 450 is rocked rearward by the rolls 451. This prevents restoring the machine to Add while a multiple stroke example is set thereon. 453 is a supplemental lever pivoted at 454 to the lever 446 and having its forward end adapted to engage the under rear side of the shaft 145 when the rear part of the lever 446 is held down by 80 the pin 423. This supplemental lever is pulled upward by a spring 455 and is limited by a stop lip 456 bent inward from the lever 446, and can operate, when depressed by the rearward part of the shaft 145, to 85 cause the elevation of the stop 448. If this stop be held down under the pivot 423 the supplemental lever can yield, slightly extending the spring 455, as the shaft 145 is rocked during the cranking operation by the 90 links 161 and 330. 457 is a pivot shaft held in suitable bearings 458 on the frame parts 7 (Figs. 7, 63, 64) and having attached thereto in each column of adding mechanism a stop arm 459 formed with stops 460 by 100 which may be arrested pins 461 attached to the sides of the front elements 11', 12' of the stop levers. 462 is a transverse bar connecting the upper ends of the arms 459, the right end of which bar is connected by a 105 link 463 with the pivot 422 of the locking link 421. When the latter is moved rearward as the locking lever 434 is depressed the stops 460 are caused to move under the pins 461 so as to hold the adding stop levers 110 11, 11', 12, 12' from being depressed and the stops 15, 16 from being thrown forward to arrest the column actuators, as might otherwise be done by depression of the adding finger keys 4 during the cranking of the 115 multiplying mechanism. The stops 460 cannot, however, be thrown into operation until the keys have been set to express the multiplicand and the locking key 171 has been depressed. The locking key cannot be 120 depressed until at least one adding key has been set, because the upturned stop 448 does not release the pin 423 and the locking key lever until the shaft 450 has been rocked rearward by the roll 451 of a multiplying 125 lever (Figs. 15, 22). Also the locking key cannot be depressed to release the power shaft until an indicator key 223 and a control mechanism has been set, and when the key is depressed it causes the power mecha- 130

nism to start the proper (highest) control into operation. 464 is a cam slot formed in the rear arm of the locking lever (Figs. 61, 63), in which engages a roll 465 mounted on the side of a middle lever 466 pivoted at 467 on the neutralizing trip shaft 415. The lever 466 is formed with right and left lateral lips 468 and 469. The said arm 414 (Fig. 63) fixed on the rock shaft 415 has its front 10 end engaging the under side of the right lip 468, and 470 is an arm, which may be a part of the arm 419, fixed on the rock shaft 388 and having its front end engaging under the left lip 469. The depending arms 416 and 15 419 attached respectively to said rock shafts are connected by the springs 417 and 390 with the said middle lever 466, whereby the ends of the two side levers are pressed against the under sides of the said right and 20 left lips. The left arm 470 has at its forward end a shoulder or notch 471 adapted to be engaged by a lateral lip 472 on the locking lever (Fig. 61^b).

On the right side of the said arm 312 (Figs. 43, 61) is fixed a pin 473, below the path of which is arranged a link 474, having a hook 475 adapted to engage the pin so that the link can be drawn rearward by the pin. 476 is a link pivoted to the forward 30 end of an arm 477 fixed on the shaft 415. This link is formed with a slot 478 which embraces a pin 479 fixed on the side of the rear end of the link 474. This hooked link is pulled downward by a spring 480 connecting it with the lower end of the arm 481, fixed on the rock shaft 298. The turning of the shaft 415 rearward is adapted, through the link 476, to raise the hook into the path of the pin 473. This pin is oscillated by the 40 main cam shaft as already described in connection with Fig. 43. The rock shaft 298, which carries the stop arms 297 (already referred to in connection with the multiple control mechanism and seen in Figs. 35 to 45 38), has attached thereto the depending arm 482 which is caused to be pulled forward by the spring 483, the latter being connected with the said arm 481, and also has fixed thereon an upwardly extending arm 484 50 formed with an outwardly extending lip 485 embraced in a slot 486 of the locking lever. This slot has a shoulder 487 above which the lip 485 may engage, when the locking lever is depressed, to lock the same 55 in such position. When the locking lever is otherwise free to be depressed, and its key 171 is pressed down, the spring 483 causes the lip 485 to engage above the said shoulder. This movement removes the arms 297 60 from their positions against the pawl cut out levers 255, as already mentioned. 488 is a pin fixed on the side of the notched cipher control finger 291, one such pin for each pair of fingers. The front side of each 65 pin is engaged by the arm 482, one arm for

each pin, fixed on the rock shaft 298. When the parts are in the position shown in Fig. 61, with the locking lever elevated; the arms 482 force the pins 488 and pairs of notched fingers 291 rearward (Fig. 62) thus relieving 70 the V-pins 290 of friction to allow of the easy upward and backward movement of the internally toothed sectors in the setting of the controls by the keys 223. When the controls have been set, and the locking key is depressed and the lip 485 springs back above the shoulder 487, the arms 482 swing a little 75 forward and allow the V-pins to bear against the front edges of the fingers, and to enter the notches thereof when the pins arrive in 80 front of the notches.

Similarly, and for the same purpose, the V-pins 270 of the externally toothed sectors are relieved of the pressure of the notched fingers 271 and 272 when the locking key is 85 elevated. When the locking lever is held up under the pull of the spring 435 (Fig. 63) the inner forward part of the slot 464 causes the arm 466 to be depressed, the right and 90 left lips of which depress the side arms 411 and 470 and rock the shafts 415 and 388 slightly forward, which rocks the said notched fingers attached to the said shafts downward enough to clear their V-pins (Fig. 62). If it be attempted to depress 95 the locking lever without setting a control the slot 464 will rock the arm 466 up, and this will rock the shafts 415 and 388 backward, by the pull of the springs 417 and 390. This lifts the arm 470 attached to the 100 shaft 388 and brings the notch or shoulder 471 in front of the lip 472 (Fig. 61^b) and holds the locking lever from being depressed. But if a control be set at 1 or more its V-pin 105 270 will no longer be over a notch 389 but will keep its notched finger down, so that when the locking lever is then depressed the slot 464 and arm 466 can no longer rock the shaft 388, and consequently the arm 470 and shoulder 471 will not be elevated to arrest 110 the lip 472 of the locking lever. In such case the lips 468 and 469 will move up away from the ends of the arms 414 and 470 and the springs 417 and 390 will be extended. The arm 470 being attached to the forward 115 rock shaft which carries the fingers whose notches extend under the V-pins when they are at normal and also when they are at 0, the setting of a control at 0 will not hold down the fingers 271 or the arm 470, and 120 consequently such a setting will not allow the locking key to be depressed, for such a setting would not be functional in a multiplying operation or in any multiple stroke example.

While the neutralizing operation is being performed the movements, to automatically release the locking key and restore it and its connected parts to normal position, are taking place. At the normal position 130

of the last control the fingers 272 are allowed to rise, as already described, and the arm 477 moves upward, raising the link 474, against the pull of its spring 480. This 5 draws the hook 475 into the path of the pin 473 as the latter is rocking backward, and the pin pulls the link backward, with the arm 481, and rocks the shaft 298 forward. This throws the lip 485 forward from above the 10 shoulder 487 and the locking lever springs up under the pull of the spring 435. This movement is accompanied by a downward movement of the arm 477 which carries the slotted link, but such downward movement 15 is allowed by the slot 478. When the shaft 100 rocks forward to its final and normal position the pin 473 releases the hooked link 474, which is then pulled down by its spring 480 out of the path of the pin.

20 When the locking key is depressed it throws into engagement with its ratchet only the driving pawl 231 of the highest set order. Although each of the arms 297 is removed from its pawl cut out lever 255 25 only the arm 238 of said highest order springs up. This is because in the lower orders the arms 238 are held down by the springs 242, while in the highest order the pin 244 (at normal position in the next 30 higher order) holds back the arm 243 and raises the pin 246 to the top of the slot 247, allowing the spring 248 to pull up the arm 238 when the arm 297 is so removed.

The following is a summary of the principal functions and effects of the locking key and its lever: The locking key is locked against depression until the key setting devices are moved from Add to Mul. or Div, until an adding key is depressed, until a 35 control is set, and during canceling, and during this time the power shaft is locked against rotation. The depression of the locking key releases the power shaft, locks the locking device of the power shaft 40 against being locked, locks the adding stop levers against depression; locks the key setting device against being returned to Add; and locks the canceling device. When the locking key rises the key setting device can 45 be returned to Add; thus disconnecting the adding machine from the multiplying mechanism; the power shaft is locked; the canceling device is released; the stop levers and adding keys are released; the V- 50 pins of the internally toothed sectors are relieved from pressure of the vertical notched fingers of the cipher control; and the V-pins of the externally toothed sectors are relieved of the pressure of the two sets 55 of horizontal notched fingers, comprised in the trans-setting lock and neutralizing mechanisms.

60 *Key set clearing device, (Figs. 8, 65, 66.)—* The function of this mechanism is to coöperate with the canceling device of the add-

ing mechanism, so that, if the machine has been set by the handle 134 for multiplication and keys have been set on the adding key board (with or without a setting of the control keys 223) for a multiply stroke 70 example, and it is discovered that the setting is wrong, the adding mechanism may be cleared by the canceling handle 53 without going through with the cranking operation or the performance of an undesired 75 example. After such a setting certain of the rack levers are locked up on the pawls 116 and the corresponding column actuators are held down below normal position, and these pawls must be released to clear the 80 machine. 489 is a clearing lever pivoted at 59 to the frame and provided with a jaw 491 which embraces the canceling cross bar 57. As to vertical position this lever is controlled by the cross bar. On the front 85 end of the lever is mounted a roll 492 which, when the cross bar is depressed by the initial movement of the canceling handle, swings down in a cam slot 493 formed in an arm 494 loose on the automatic actuator 90 release rock shaft 120, and having fixed therein a lateral pin 495 arranged to engage the rear side of an arm 496 fixed on the rock shaft. The said cam slot is of such form that when the roll swings down the 95 arms and shaft are caused to rock rearward and release the pawls 116, in a manner already described but now from a different source of actuation. When the pawls 116 are released as first described, in the 100 course of the operation of the multiplying mechanism, the arm 496 swings away from the pin 495 without movement of the arm 494 or lever 489.

105 *The frame.—* The frame is constructed with a view to facilitating the assembly of the machine, and to allow of the multiplying mechanism being opened up to get at the interior and lower operating parts. 497 indicates longitudinal vertical plates, which 110 in location are upward continuations of the division plates 1 of the adding machine. With the frame plates 497 are combined supporting and protecting right and left side plates 498 and 499. 500 is a reinforcing plate (Figs. 3, 6, 60), one at each side of the machine, arranged along the outer side of the outer frame plate 1. All of these plates are braced apart by tubular spacers 501 and are clasped together by the 115 tie rods 3 passing through apertures in the plates and through the spacers. The tie rod 3 at the upper rear corner of the adding machine frame is united pivotally with the frame plates 497 which hinge on the said 120 tie rod. On the upper intermediate tie rod of the adding machine frame the forward ends of the plates 497 rest, by slots 502 formed in the plates and embracing the rod (Fig. 4), the said spacers 501 being em- 125 130

ployed between the slotted ends of the plates. All of the plates are clamped together by screws 503 in the ends of the tie rods. 504 is a locking rod which passes laterally from side to side of the machine through alined apertures in the plates 1 and 497. By removing the locking rod and loosening the necessary tie rod screws 503 the plates 497, as a connected frame, may 10 turn upward and backward on the said tie rod 3, carrying with them the multiple control mechanism and related parts which are mounted in the said frame. Most of the transverse pivot rods are laterally 15 insertible in and through the frame and through the bearing apertures of the pivoted parts.

In Fig. 48^a is illustrated the preferred construction by which the frame parts, 20 spacers, tie rods and the end screws of the latter are assembled and united, in which the tie rod passes through the outside frame part, and the said frame part is held against the contiguous spacer by the screw head, the 25 screw being tapped into the end of the tie rod. Bearings for rotating or rocking parts may be attached to the frame parts as illustrated in the said figure, the tubular end of such bearing being inserted through the 30 frame part and then spread, expanded or upset on the face of the frame part, as indicated at 505.

Operation.—In order to make the 35 functions of the different parts and mechanisms more clearly understood, I will describe briefly and consecutively the essential movements comprised in a complete operation of the machine.

The setting handle 134 is first adjusted, 40 say to Mul, which causes the front rock shaft 145 to be turned forward, allowing the links of the column actuators to engage with the lugs on the front arms of the multiplying levers.

45 Keys of the adding machine are now depressed, to properly express the multiplier; whereby the column actuators are depressed and the rack levers elevated and held up for the moment by their pawls 116. Also the roll 451 on any front multiplying 50 lever arm turns the rear rock shaft 450, dropping the lip 450" so as to hold the setting cam 146 (Fig. 17) from being turned forward to Add (although it could still be 55 turned back to Div.).

Control keys 223 suitable to express the 60 multiplier are now depressed, which releases the outer and inner toothed sectors and allows them to turn forward and backward, respectively, until the outer sectors are stopped by the feet 224 of the control keys. At the same time the indicator wheels turn 65 backward to the proper points so that their exposed numerals properly designate the multiplier. The said movement of the sec-

tors removes their V-pins from in front of the notches in the horizontal and vertical controlling fingers 271, 272, 291. The lock key 171 is now depressed. This releases the main stop pawl 190 so that the power shaft 70 is freed; locks up the stop levers of the adding mechanism by the locking frame (Fig. 64), so as to prevent interference by mismanipulation, which might result from depressing any of the adding keys during 75 the cranking operation, which would be likely to throw the adding stops in at higher points of depression than the column actuators have been set for; brings the horizontal notched controlling fingers up against 80 their V-pins, brings the vertical notched controlling fingers up against their V-pins (Figs. 60 to 62), releases the actuating pawl arms 238 in all orders by removing the stop arms 297 from in front of the pawl cut out 85 levers 255 (Fig. 37); and it also holds down continuously the locking lever 446 (Figs. 16, 17), which acts to lock the locking key lever until the adding keys were depressed.

The machine is now free and the example 90 can be performed by the continuous turning of the power shaft by the crank, or other motor. The first backward turning of this power shaft causes the main rock shaft to be turned forward for about 18°, from the 95 position shown in Fig. 22. By this movement the dog pawls are released and the parts of a set multiplying lever are locked together, each with its proper capacity for the additive throw. In this movement the 100 left hand toggle (Figs. 18, 27), is caused to be broken. The setting and sustaining pawls of the rack levers are now released.

The highest control of those which have 105 been set now begins to operate, step by step, carrying the externally toothed sector rearward with its V-pin 270, pin 244 and latch 273, and the internally toothed sector moving forward and downward with its V-pin 290 and pin 289. The first step which the 110 highest control thus makes corresponds with the accumulation of the adding mechanism, which was caused by the setting of the keys of the adding machine. A little further movement of the main cam shaft causes the 115 column actuators to be released, which spring up and cause the first accumulation to be shown upon the adding machine wheels.

The main rock shaft now begins its back- 120 ward rock, whereupon the hooked link (Figs. 27, 28) disengages its hook from pin 192, and the rear ends of all of the said multiplying levers descend to normal position.

If 1 was set on the first control, the cipher 125 control mechanism operates on this same motion, the V-pin (Fig. 40) having arrived opposite to its notch on the first short forward rock of the main cam shaft, and the notched finger having moved forward. On 130

the first backward rock the slotted pawl 326 is engaged, the rock shaft 325 is turned, the links 330 are thrust forward to disengage the column actuator links, the latch arm 334 5 swings forward (Fig. 41), the latch tooth 336 swings up and temporarily holds the latch arm 334 forward while the rear ends of the multiplying levers go up one stroke without causing any addition, and the rear 10 arm of the said latch rests against the rear swinging bar 338. The latch 273 of the highest set control has now, at 0 position, arrived under the lateral pin 306 of the rock shaft 305, (Fig. 44) and is depressed 15 thereby.

The main shaft now begins a forward rock. This raises the rear ends of the set multiplying levers but does not depress the disconnected column actuators; turns the indicator wheel of the highest control from 0 20 to normal, forcing rearward the vertical notched fingers 291, the V-pin having now passed down below its notch releases the pawl 326 from the tooth 323 so that during 25 the turning of the indicator wheel the arm 280 on the externally toothed sector pushes back the arm 285 and turns the rock shaft 286 backward (Fig. 46) thus carrying its end arm 387 from under the lip 385 on the 30 upper arm of the link lever, whereupon the said link can (on the backward rock of the main shaft) be let back by its cam and pulled back by its spring 376, to allow the pin 378 to come down above its rear hook 35 377. At the same time the pin 289 on the arm of the internally toothed sector (Fig. 35) engages the arm of the pawl cut out lever 255 forcing it down (Fig. 39) and throwing the stop 260 into line with the 40 lateral projection 259 on the toothed segment 234. Then the pin 244 on the externally toothed sector (Fig. 34) presses back the arm of the throw-in lever 243 (Fig. 37), which throw-in lever has its front arm and 45 pawl controlling flange 239 located in the next lower order. This allows the pawl 231 of said next lower order to engage its ratchet 226.

The main shaft now rocks backward. 50 The rear end of the multiplying levers descend to their lowest position and the pin 378 (Fig. 47) pulls the trans-setting link 373 down to press the dogs fully inward by a rocking of the trans-setting shaft of 55 sufficient degree for that purpose. This also restores the left hand toggle 208 from the position shown in Fig. 28 to that shown in Fig. 27. Also the right hand arm 349 on the trans-setting shaft (Fig. 40) rocks forward, 60 operating through the toggle 350 to swing the bar 338 backward so as to rock the latch tooth 336 down and allow the arm 334 of the cipher control throw-out to swing back over the tooth and release the column actuator links 139 so that they may reengage 65

the multiplying levers (unless the lowest control is at 0). After this has been done the trans-setting shaft 218 has caused the toggle arm 353 to encounter the fixed pin 354, the toggle is broken and the bar 338 70 swings forward. At the same time the slotted arm 251 on main shaft (Fig. 39) presses the toothed segment 234 downward, the projection 259 on which presses on the end of the pivoted stop 260 and throws out the 75 pawl, whereupon the said pivoted stop snaps under the arm of the pawl cut out lever 255 and the latter is held out until there is a re-setting for a new example. At the same time the upper cam arm 235 on the toothed 80 segment rocks forward and cams up the roll 284 on the pushing arm 280, raising the same to normal position (Fig. 47), allowing the trans-setting trip shaft 286 to rock forward to its normal position under the pull of the 85 spring 316 (Fig. 48).

The main cam shaft now rocks forward, which causes the trans-setting, to lower orders, of the adding mechanism, to be completed, and the trans-setting shaft 218 rocks 90 back to normal position. Also the cam 380 (Fig. 47) draws the trans-setting link forward away from its depressing pin 378. The trans-setting link 373 and arm 374 have now been raised by the trans-setting shaft 95 376 and spring 376. Finally the cam slot 380 presses up the roll 384, link 373 and arm 374 and they are latched up on the latch 387, (Fig. 6).

When the lowest control comes to the 0 100 position, the V-pin shown on the externally toothed sector rides into the notch of the right hand control finger 271 (Fig. 56), and all higher fingers being at the normal position with their notches under the V-pins, 105 all of said fingers can now rise allowing the rock shaft 388 to be rocked backward by its spring 390 (Fig. 55). This latches up the trans-setting link 373 (Fig. 56) and prevents it from causing the dogs to be locked 110 to the outer racks of the rack levers.

On the next step of the lowest control from 0 to normal (which occurs at about the end of a forward rock of the main shaft, Fig. 58) the left hand fingers 272 can all 115 rise, each finger having its notch 418 under the corresponding V-pin 270, whereupon the neutralizing link trip rock shaft 415 is rocked rearward. This turns the latch 410 back, releasing it from under the neutralizing link arm 400 (Fig. 58) and during this action the left arm 477 (Figs. 60, 61) pulls up the link 476, the slot 478 of the link lifts the pin 479 on the hook link 474, and the hook link, so that the hook will be in the 125 path of the pin 473 on the segment arm 312 to be actuated at a later time.

The main shaft now rocks rearward, so that the pins 396 engage the hook of the neutralizing link (Fig. 59), rocking the 130

trans-setting shaft only sufficiently so that the dogs are forced inward to their neutral position. At the same time the backward rock of the main shaft causes the pin 308 on the arm 307 fixed on the shaft to force the slotted arm 309 backward (Fig. 61), and the roll on the slotted arm and located in the slot 311 on the segment arm 312 rocks the said segment arm backward. This pulls the hooked link backward and turns the rock shaft 298 forward. This rocks the lip 485 on the upper arm 484 out of the notch 487 in the locking key lever 434, allowing the spring 435 (Fig. 63) to pull the locking key lever up to normal position. At the same time the arm 482 on the said rock shaft 298 (Fig. 62) presses rearward all of the cipher control fingers away from the V-pins of the sectors, thereby preventing any friction of the sectors on the pins when the controls are to be initially set for a new example. The rocking of the said shaft 298 also brings all its arms into position to lock the pawl cut out levers 255 as shown in Fig. 35.

When the locking key lever rises its slot 464 causes the lever 466 to be rocked downward (Fig. 61), whereby the lips of the said lever press down the levers 414 and 470 at its sides and rock forward the two rock shafts 415 and 388. This depresses the notched fingers of the trans-setting lock shaft and of the neutralizing shaft away from the V-pins of the externally toothed sectors, so as to relieve them also of friction. By the same movement of the neutralizing shaft the slotted link 476 drops down relative to the pin 479 in its slot (Fig. 61). During the upward movement of the locking key lever, the lever 428 is rocked so as to unlock the canceling shaft, to throw in the power shaft locking pawl 190, to release the horizontal locking lever 446 (Figs. 16, 63), and to swing forward the locking frame (Fig. 64) to release the adding stop levers.

As the main shaft is thus finally rocked forward, the pin 308 (Fig. 61) allows the slotted arm 309 and segment arm 312 to turn forward under the pull of the spring 313 which is attached to the segment arms, allowing the hooked link 474 to drop until it is arrested by its pin at the bottom of the slot 478 in the vertical slotted link 476. The crank handle is now arrested by the main pawl 190 leaving all parts of the machine in normal position ready for a new setting and the performance of a new example.

If, before the locking key has been depressed, it is discovered that the adding keys have been erroneously set, the setting may be cleared by the canceling handle; and if it be discovered that the controls have been mis-set they may be pushed back to 0 by the slides 293 and re-set correctly, unless one or more of the controls require to be

set at normal. In the latter case such slides may be flipped back with force enough to throw the control mechanisms past 0 to normal, which is allowed by the slots 294. If the locking key has been depressed the controls may all be pushed forward to 0 and the machine rapidly cleared by cranking. Or the controls may all be flipped back to normal, and the adding mechanism cleared by the canceling handle. If error is found in the middle of an example it is advisable to push all controls to 0 and clear by cranking.

Division.—To perform division with the new mechanism it is well perhaps to first understand that the comptometer unlike the crank operated multiplying and dividing machines, performs subtraction and division by the adding of complements of the item to be subtracted to that of the item from which it is to be subtracted, preventing the carrying of the tens at the left, in subtraction, and allowing it to take place in division, thus recording each subtraction and leaving the answer and remainder on the accumulator wheels. To facilitate the adding of the complement, the keys are provided with a co-digital marking, as will be noted in Fig. 1, so that the number to be subtracted may be struck on the keys by the co-digits, or small figures instead of the large. There is a rule in using the co-digits that one must always bear in mind, that is; where the item representing the figure to be subtracted is struck, the lowest figure or digit of that item must be struck one count lower, that is; if the figure to be subtracted is 2463 it should be struck as 2462, thus adding its complement 7537, whereas if the item should be 2460 it would be struck 2450, adding its complement 7540.

The preferred mode of operation, in the use of the machine herein illustrated, is as follows: The dividend is first set up on the keys of the adding machine, the handle 134 being set at Add and the multiplying mechanism being disconnected. The dividend may thus be set in any convenient places upon the adding wheels. If set at the extreme right, however, the division cannot be carried into decimals but a remainder will be left which will be the numerator of a vulgar fraction. The dividend is not, however, to be set at the extreme left of the adding wheels, it being necessary to leave places at the extreme left for the display of the quotient. The handle is then operated to set the machine at Div. The machine would operate the same if it was set at Mul. excepting that in such case the mechanical signal caused by the lever 167 and notch 164 would not be felt by the operator, and it would not be so apparent at just what time a subtraction was complete. The divisor is

now set upon the keys of the adding machine, in the same places which contain sufficient of the left hand portion of the dividend to contain such divisor. In thus setting the divisor the codigital markings of the finger keys of the adding machine are to be used, which markings are usually shown by figures smaller than the normal figure markings used in addition, and the right hand digit of the divisor must be set, as usual in subtraction, one place lower, by codigital marking, than its real value. This setting of the divisor does not now actuate the adding numeral wheels, the column actuators being held by the multiplying levers. The multiple stroke control indicator mechanisms and wheels are now all set at 9. It would be sufficient if they were given such setting as would contain the quotient, but the quotient being at present unknown, it is not necessary to take any time in estimating its amount, and the setting of all controls at 9 will be sure to contain it. Controls at the left of the lowest figure of the divisor need not be set and may remain at normal. The machine is now in such condition that it contains (in the dividend first set) in effect a minuend which, by the cranking operation, may be rapidly diminished, in the proper places successively, until there is nothing left of it excepting a remainder which is less than the divisor, and the number of additive strokes made in so diminishing the minuend (or dividend) will be the quotient which is sought. In order to automatically keep count of such strokes, one or more of the adding machine keys immediately at the left of the highest place occupied by the dividend are set at 9, the effect of which is (during the multiplying operation, together with the carrying to the left, which carrying is not interrupted) to carry 1 to the left for every additive stroke of the combined adding and multiplying mechanism. The locking key having been depressed, the cranking operation is now begun and may be performed with great rapidity, it only being necessary for the operator to observe the remainder left at each stroke, at the instant when he feels the said mechanical signal. The remainder appears on the numeral wheels about one third of a crank revolution before the signal is felt. At whatever such time the remainder is seen to be less than the divisor the operator stops the cranking operation with the lever 167 engaged with the notch 164, and returns to 0 the highest and heretofore active control, which is done by pushing forward on the rear end of the control slide 293. When such slide is fully inward its control mechanism and indicator wheel will be set at 0. When the control is thus set no further additive or subtractive effect is produced until the operation of the next control begins

in the next lower places or orders of the adding machine to the right, but the control is set at 0 in order that its last step from 0 to normal may give a trans-setting of the divisor, or, more literally speaking, the complement of the divisor, one place to the right. If now the remainder is still less than the divisor the now highest control is set at 0, and so on, which is analogous to bringing down ciphers to the right in ordinary long division, until there is a sufficient remainder to contain the divisor. Then the cranking operation is resumed and continued, with the necessary pauses to push forward the control slides, as may be necessary, until the ultimate remaining part of the dividend is less than the divisor. This remainder may be expressed in the form of a vulgar fraction, or the above described operations may be continued into decimals, to such extent as the numeral adding wheels at the right of the machine permit. Each of the above additive strokes has accumulated 1 on the adding wheels at the extreme left, such accumulations being first in the highest place of the quotient, then, after the divisor has been trans-set to the right, in the next highest place of the quotient, and so on to unity, or below unity in the form of decimals. This accumulation of additive strokes at the left gives an accurate showing on the adding numeral wheels of the quotient sought; excepting that a vulgar fraction, being a part of the quotient, is to have its numerator read according to the remainder on the right hand adding wheels.

From the foregoing description it will be noted that the machine when set for multiplication and division becomes a key set crank operated machine, capable of automatically transferring its key setting from left to right through the medium of the multiple stroke control, the capacity of transfer and repetition of additive actuators depending on the setting of said stroke control. To the average inventor or mechanic who is familiar with adding and listing machines it will be noticeable that this machine contains features that have long been sought, to wit; the combining of the crank operated calculating machine with the key operated calculating machine, without losing the light action so desirable in a key driven calculating machine, and having also the properties of the crank operated devices.

The terms "multiplying" and "multiplying mechanism" as herein used are generally inclusive of division and all calculations involving repetitions of the same number, whether positive or negative. It will be understood that the machine embodying the invention might be constructed to operate from right to left, with trans-setting in such direction, but the left to right direction is advantageous allowing the end of a computa-

tion to be carried into decimals, and giving greater capacity in computation. In multiplication either factor may be set on the adding machine, or on the multiple control mechanism. The operation is shorter if the smaller factor, or that which represents the fewer number of strokes, be set on the multiple control indicator.

My invention is hereinabove set forth as embodied in one particular form of construction, but I do not limit it thereto or to less than all the possible forms in which the said invention as hereinafter claimed may be embodied and distinguished from prior devices.

What is claimed is:

1. In a multiple-order key-driven calculating machine, in combination: accumulator mechanism including numeral wheels; denominational series of keys for actuating the said accumulator mechanism; multiplying mechanism arranged in a plurality of orders; means whereby orders of the multiplying mechanism may actuate orders of the accumulator mechanism for the accumulation of the product; and a supporting framework permanently joining the above parts in such manner in a unitary machine that the said accumulator mechanism may be actuated either by the keys or by the multiplying mechanism; substantially as specified.

2. In a multiple-order key-driven calculating machine, in combination: accumulator mechanism including numeral wheels; denominational series of keys for actuating the said accumulator mechanism; automatic multiplying mechanism arranged in a plurality of orders and having means in said orders for setting up at one time a factor which comprises a plurality of denominations; means for connecting a plurality of orders of the said multiplying mechanism with a plurality of orders of the said accumulator mechanism irrespective of the said keys; and a single actuating device whereby the multiplying mechanism and accumulator mechanism are operated to perform automatically the multiplying operation without further factor-setting manipulation; substantially as specified.

3. In a multiple order key-driven calculating machine, in combination: accumulator mechanism; denominational series of keys for actuating the said accumulator mechanism; multiplying mechanism comprising a plurality of orders for performing in connection with the said key-driven accumulator mechanism and automatically the entire multiplying operation; and means whereby a plurality of orders of the multiplying mechanism are connected at one setting with a plurality of orders of the accumulator mechanism without factor-setting manipulation; substantially as specified.

4. In a multiple order calculating ma-

chine, in combination: adding mechanism arranged in successive orders; ordinal sets of finger keys arranged to drive the orders of adding mechanism; crank driven devices for actuating the orders of the adding mechanism; and means for converting at will the key driven adding mechanism to a key set mechanism by connecting orders of the adding mechanism with the said crank driven devices.

5. In a multiple order calculating machine, in combination: adding mechanism arranged in successive orders; ordinal sets of finger keys arranged to drive the orders of adding mechanism; crank driven devices for actuating the orders of the adding mechanism; means for converting at will the key driven adding mechanism to a key set mechanism by connecting orders of the adding mechanism with the said crank driven devices; and locking means for the keys of the adding mechanism to prevent the same from interfering with the said crank driven devices when the machine is converted to the said key set form.

6. In a multiple order calculating machine, in combination: adding mechanism arranged in successive orders; ordinal sets of finger keys arranged to drive the orders of adding mechanism; crank driven devices for actuating the orders of the adding mechanism; means for converting at will the key driven adding mechanism to a key set mechanism by connecting orders of the adding mechanism with the said crank driven devices; and locking means for the crank driven devices to prevent the same from interfering with the adding mechanism when the machine is converted to the said key driven form.

7. In a multiple order calculating machine, in combination: adding mechanism arranged in successive orders; ordinal sets of finger keys arranged to drive the orders of adding mechanism; crank driven devices for actuating the orders of the adding mechanism; means for converting at will the key driven adding mechanism to a key set mechanism by connecting orders of the adding mechanism with the said crank driven devices; locking means for the keys of the adding mechanism to prevent the same from interfering with the said crank driven devices when the machine is converted to the said key-set form; and locking means for the crank driven devices to prevent the same from interfering with the adding mechanism when the machine is converted to the said key driven form.

8. The combination of adding mechanism arranged in successive orders; ordinal sets of finger keys arranged to drive the orders of adding mechanism; crank driven devices for actuating the orders of the adding mechanism; and means for converting at will the

- key driven adding mechanism to a key set mechanism by connecting orders of the adding mechanism with the said crank driven devices.
- 5 9. The combination of adding mechanism arranged in successive orders; ordinal sets of finger keys arranged to drive the orders of adding mechanism; a multiple stroke mechanism arranged in successive orders;
- 10 means for driving the multiple stroke mechanism; and means for converting at will the key driven adding mechanism to a key set mechanism by connecting orders of the adding mechanism with orders of the multiple stroke mechanism.
- 15 10. In a multiple order calculating machine, in combination: adding mechanism arranged in successive orders; ordinal sets of finger keys arranged to drive the orders of adding mechanism; a multiple stroke mechanism arranged in successive orders; means for driving the multiple stroke mechanism; and means for converting at will the key driven adding mechanism to a key set mechanism by connecting orders of the adding mechanism with one or more orders of the multiple stroke mechanism.
- 20 11. In a multiple-order key-driven calculating machine, in combination: accumulator mechanism; denominational series of keys for actuating the said accumulator mechanism; multiplying mechanism comprising a plurality of orders for performing in connection with the said accumulator mechanism and automatically the entire multiplying operation; and means whereby a plurality of orders of the multiplying mechanism are connected at one setting with a plurality of orders of the accumulator mechanism without further factor-setting manipulation; and means for disconnecting at will the said multiplying mechanism from the said accumulator mechanism, to leave the latter free for additive operation when driven by the said keys; substantially as specified.
- 25 12. In a multiple-order key-driven calculating machine, in combination: accumulator mechanism; denominational series of keys for actuating the said accumulator mechanism; multiplying mechanism comprising a plurality of orders for performing in connection with the said accumulator mechanism and automatically the entire multiplying operation; means whereby a plurality of orders of the multiplying mechanism are connected at one setting with a plurality of orders of the accumulator mechanism without further factor-setting manipulation; and a single actuating device whereby the necessary movements for multiplication are communicated to the said multiplying mechanism and accumulator mechanism; substantially as specified.
- 30 13. In a multiple-order key-driven calculating machine, in combination: accumulator mechanism including numeral wheels; denominational series of keys for actuating the said accumulator mechanism; automatic multiplying mechanism arranged in a plurality of orders and having means in said orders for setting up at one time a factor which comprises a plurality of denominations; means for connecting a plurality of orders of the said multiplying mechanism with a plurality of orders of the said accumulator mechanism irrespective of the said keys; a single actuating device whereby the multiplying mechanism and accumulator mechanism are operated to perform automatically the multiplying operation; and means for disconnecting at will the said orders, to leave the accumulator mechanism free for additive operation when driven by the said keys; substantially as specified.
- 35 14. In a multiple-order key-driven calculating machine, in combination: accumulator mechanism including numeral wheels; denominational series of keys for actuating the said accumulator mechanism; multiplying mechanism arranged in a plurality of orders; means whereby orders of the multiplying mechanism may be connected at will with the actuated orders of the accumulator mechanism for the accumulation of the product; and a supporting framework permanently joining the above parts in such manner in a unitary machine that the said accumulator mechanism may be actuated either by the keys or by the multiplying mechanism; substantially as specified.
- 40 15. In a multiple-order key-driven calculating machine, in combination: accumulator mechanism including numeral wheels; denominational series of keys for actuating the said accumulator mechanism; multiplying mechanism arranged in plurality of orders; means whereby orders of the multiplying mechanism may actuate orders of the accumulator mechanism for the accumulation of the product; and means for disconnecting the multiplying mechanism from the accumulator mechanism to leave the latter free for separate operation, when driven by the said keys, without removing the multiplying mechanism; substantially as specified.
- 45 16. In a multiple order calculating machine, in combination: adding mechanism arranged in successive orders; ordinal sets of finger keys arranged to drive the orders of adding mechanism; a multiple stroke mechanism arranged in successive orders, and comprising stroke control mechanism whereby a connection of the multiple stroke mechanism is automatically trans-set to another order after a predetermined number of strokes; and means for converting at will the key driven adding mechanism to a

key set mechanism by connecting orders of the adding mechanism with orders of the multiple stroke mechanism.

17. In a multiple-order key-driven calculating machine, in combination: accumulator mechanism including numeral wheels; denominational series of keys for actuating the said accumulator mechanism; multiplying mechanism arranged in a plurality of orders and having means in said orders for setting up at one time a factor comprising a plurality of denominations; devices whereby a plurality of orders of multiplying mechanism are connected irrespective of the said keys with a plurality of orders of accumulating mechanism for the accumulating of the product on said numeral wheels; trans-setting mechanism operating between said orders of multiplying mechanism to automatically cause them to actuate successively the orders of accumulator mechanism; a single actuating device whereby the multiplying mechanism and accumulator mechanism are operated to perform automatically the multiplying operation; and means for disconnecting at will the said connected orders, to leave the accumulator mechanism free for separate operation when driven by the said keys; substantially as specified.
18. In a multiple-order key-driven calculating machine, in combination: accumulator mechanism including numeral wheels; denominational series of keys for actuating the said accumulator mechanism; multiplying mechanism arranged in orders at the rear of the accumulating mechanism and having a plurality of its orders connected with a plurality of orders of accumulator mechanism; and means for actuating the connected multiplying mechanism and accumulator mechanism; substantially as specified.
19. In a multiple-order key-driven calculating machine, in combination: accumulator mechanism including numeral wheels; denominational series of keys for actuating the said accumulator mechanism; multiplying mechanism arranged in orders at the rear of the accumulating mechanism and having a plurality of its orders connected with a plurality of orders of accumulator mechanism; and means for causing the connected orders of multiplying mechanism to act automatically successively on the connected orders of accumulator mechanism, for the accumulation of the product; substantially as specified.
20. In a calculating machine, in combination with adding mechanism comprising multiple order accumulator mechanism, and digitally actuating column actuators for driving the same; keys whereby power is stored for the driving of the column actuators; and automatic multiplying mecha-
- nism having means for connecting the same with the said column actuators and causing the adding mechanism to be key-set; substantially as specified.
21. In a calculating machine, the combination of orders of adding mechanism, having column actuators, means for setting certain of said orders to have predetermined additive movement, and means for trans-setting the settings of the said column actuators successively from one order to another.
22. In a calculating machine, the combination of orders of adding mechanism, having column actuators, a power mechanism for actuating the said column actuators, means for selectively connecting certain of the said column actuators with the power mechanism each for a predetermined individual additive movement, and means for trans-setting the said connections from one column actuator to another while maintaining the original individual additive effect of the said connections.
23. In a calculating machine, the combination of orders of adding mechanism having column actuators, independently actuating orders of multiple stroke mechanism, means for connecting all of the said column actuators with the multiple stroke mechanism, means for driving the multiple stroke mechanism, setting means for rendering certain of the orders of multiple stroke mechanism automatically active for predetermined numbers of additive movements, and means for automatically trans-setting the connections between the orders of adding mechanisms and the driving means.
24. In a calculating machine, in combination; accumulator mechanism; column actuators; denominational series of keys; multiplying mechanism arranged in orders; connecting devices whereby certain of said multiplying orders respectively may be united at will with certain of said column actuators to give adding movement to them; and driving means for actuating the said orders of multiplying mechanism; substantially as specified.
25. In a calculating machine, in combination; accumulator mechanism; column actuators; denominational series of keys; multiplying mechanism arranged in orders; connecting devices whereby certain of the orders may be united at will with certain of said column actuators to give adding movement to them; driving means for actuating the said orders of multiplying mechanism; and controlling means whereby the number of such actuations is automatically determined; substantially as specified.
26. In a calculating machine, in combination; accumulator mechanism; column actuators; denominational series of keys; multiplying mechanism arranged in orders; con-

- necting devices irrespective of the said keys whereby certain of the orders may be united at will with certain of said column actuators to give adding movement to them; and driving means for actuating the said orders of multiplying mechanism; substantially as specified.
27. In a calculating machine, in combination; accumulator mechanism; column actuators; denominational series of keys; multiplying mechanism arranged in orders; connecting devices whereby certain of the orders may be united at will and, as determined by the actuation of the keys, with certain of said column actuators to give adding movement to them; and driving means for actuating the said orders of multiplying mechanism; substantially as specified.
28. In a calculating machine, in combination; accumulator mechanism; column actuators; denominational series of keys; multiplying mechanism arranged in orders; connecting devices irrespective of the said keys whereby certain of the orders may be united at will and, as determined by the actuation of the keys, with certain of said column actuators to give adding movement to them; driving means for actuating the said orders of multiplying mechanism; and controlling means whereby the number of such actuations is automatically determined; substantially as specified.
29. In a calculating machine, in combination; accumulator mechanism; column actuators; denominational series of keys; multiplying mechanism arranged in orders; connecting devices irrespective of the said keys whereby certain of the orders may be united at will with certain of said column actuators to give adding movement to them; driving means for actuating the said orders of multiplying mechanism; and controlling means whereby the number of such actuations is automatically determined; substantially as specified.
30. In a calculating machine, in combination; accumulator mechanism; column actuators; denominational series of keys; multiplying mechanism arranged in orders; connecting devices whereby certain of the orders may be united at will and, by the actuation of the keys, with certain of said column actuators to give adding movement to them; driving means for actuating the said orders of multiplying mechanism; and controlling means whereby the number of such actuations is automatically determined; substantially as specified.
31. In a calculating machine, in combination with key driven adding mechanism comprising multiple order accumulator mechanism, and digitally actuating column actuators for driving the same: automatic multiple stroke mechanism; and means for connecting the same with the said column actuators and causing the adding mechanism to be key-set; substantially as specified.
32. In a multiple-order calculating machine, in combination: denominational series of keys, accumulator mechanism, column actuators adapted to be driven, and also to be set, by the action of the keys and having means whereby they actuate the accumulator mechanism, segment ratchet levers adapted to be connected with the column actuators and to be free therefrom, means for holding the column actuators and the said levers in set position, and a setting device for connecting at will the column actuators with the said levers, whereby the machine may be used at will as a light action key driven machine independent of the said levers; substantially as specified.
33. In a multiple-order calculating machine, in combination: denominational series of keys, adding mechanism, column actuators arranged to be driven by the keys, multiplying levers, means for actuating the multiplying levers, and means connecting the multiplying levers with the column actuators.
34. In a multiple-order key-driven calculating machine, in combination: accumulator mechanism, including numeral wheels and column actuators; denominational series of keys for actuating the said accumulator mechanism; automatic multiplying mechanism having a plurality of orders; connections whereby a plurality of orders of the multiplying mechanism are connected at one setting with a plurality of the said column actuators irrespective of the said keys; and a single actuating device whereby the multiplying mechanism and column actuators are operated to perform automatically the multiplying operation; substantially as specified.
35. In a multiple-order key-driven calculating machine, in combination: accumulator mechanism including numeral wheels and column actuators; denominational series of keys for actuating the said accumulator mechanism; automatic multiplying mechanism having a plurality of orders; connections whereby a plurality of orders of the multiplying mechanism are connected at one setting with a plurality of the said column actuators irrespective of the said keys; and a single actuating device whereby the multiplying mechanism and column actuators are operated to perform automatically the multiplying operation; and means for disconnecting at will the said column actuators from the said multiplying mechanism to leave them free for additive operation when driven by the said keys; substantially as specified.

36. In a calculating machine, in combination: multiple order accumulator mechanism comprising numeral wheels and carrying mechanism; self-controlled key-driven actuating mechanism for digitally actuating the accumulator mechanism; automatic multiple stroke mechanism; and means for connecting the same with the said actuating mechanism and causing the latter to be key-set; substantially as set forth.

37. A unitary calculating machine having, in combination: accumulator mechanism; multiple order devices for actuating the said accumulator mechanism; power mechanism for giving motion to said multiple order actuating devices; automatic controlling means to control the movements of the said multiple order actuating devices; devices for setting the said automatic controlling means; and devices for determining the additive degree of movement of the said multiple order actuating devices; whereby the factors of the calculation, both having more than one place, may be set and thereafter the calculation automatically performed.

38. In a multiple order calculating machine, in combination: adding mechanism; means for setting the adding mechanism; multiple stroke mechanism for actuating the adding mechanism; control mechanism for automatically determining the number of additive strokes of the said multiple stroke mechanism; and a power device for actuating the said multiple stroke mechanism and the said control mechanism.

39. In a calculating machine, the combination of orders of adding mechanism, means for setting certain of said orders to have predetermined additive movement, and means, independent of the aforesaid setting means, for trans-setting the settings of the said orders successively from one order to another.

40. In a calculating machine, the combination of orders of adding mechanism, means for setting certain of said orders to have predetermined additive movement, and automatic means for trans-setting the settings of the said orders successively from one order to another.

41. In a calculating machine, the combination of orders of adding mechanism, a power mechanism for actuating the said orders of adding mechanism, means for selectively setting and connecting certain of the said orders with the power mechanism each for a predetermined individual additive movement, and means, independent of the aforesaid setting means, for trans-setting the said connections from one order to another while maintaining the original individual additive effect of the said connections.

42. In a calculating machine, the combination of a series of multiple stroke levers

arranged side by side, means for giving to successive levers various additive strokes, and means for trans-setting such strokes in the same succession, and length, to other of the levers.

43. In a calculating machine, the combination of a set of multiple stroke levers, each having means for setting it in connection with an order of adding mechanism, and means for trans-setting the said setting of each lever from one to another of said levers.

44. In a calculating machine, the combination of a series of multiple stroke elements, means for setting successive of said elements to have various additive movements, and means for trans-setting the settings of said multiple stroke elements, in the same succession, and extent, to other of the said elements.

45. In a calculating machine, the combination of a series of multiple stroke levers arranged side by side, means for giving to successive levers various additive strokes, and automatic means for trans-setting such strokes in the same succession, and length, to other of the levers.

46. In a calculating machine, the combination of a set of multiple stroke levers, each having means for setting it in connection with an order of adding mechanism, and means for automatically trans-setting the said setting of each lever from one to another of said levers.

47. In a calculating machine, the combination of a series of multiple stroke elements, means for setting successive of said elements to have various additive movements, and automatic means for trans-setting the settings of said multiple stroke elements, in the same succession, and extent, to other of the said elements.

48. In a calculating machine, the combination of orders of adding mechanism, independently actuating orders of multiple stroke mechanism, means for connecting all of the orders of adding mechanism with the multiple stroke mechanism, means for driving the multiple stroke mechanism, setting means for rendering certain of the orders of multiple stroke mechanism automatically active for predetermined numbers of additive movements, and means for automatically trans-setting the connections between the orders of adding mechanisms and the driving means.

49. In a calculating machine, the combination of orders of adding mechanism, means for setting certain of said orders to have predetermined additive movement, means for trans-setting the settings of the said orders successively from one order to another, and control mechanism for causing a predetermined number of strokes in each of such settings.

50. In a calculating machine, the combi-

nation of orders of adding mechanism, means for setting certain of said orders to have predetermined additive movement, automatic means for trans-setting the settings 5 of the said orders successively from one order to another, and control mechanism for causing a predetermined number of strokes in each of such settings.

51. In a calculating machine, the combination of orders of adding mechanism, a power mechanism for actuating the said orders of adding mechanism, means for selectively setting and connecting certain of the said orders with the power mechanism each 10 for a predetermined individual additive movement, means for trans-setting the said connections from one order to another while maintaining the original individual additive effect of the said connections, and control mechanism for causing a predetermined 15 number of strokes in each of such settings.

52. In a calculating machine, the combination of orders of adding mechanism, independently actuating orders of multiple 20 stroke mechanism, means for connecting all of the orders of adding mechanism with the multiple stroke mechanism, means for driving the multiple stroke mechanism, setting means for rendering certain of the orders of 25 multiple stroke mechanism automatically active for predetermined numbers of additive movements, means for automatically trans-setting the connections between the orders of adding mechanism and the driving means, 30 and control mechanism for automatically determining the number of additive strokes in 35 each of such settings.

53. In a multiple-order calculating machine, in combination: denominational series 40 of keys, multiple order adding mechanism adapted to be driven by said keys, multiple stroke mechanism having connections with said adding mechanism to operate various orders of the same, and means for automatically 45 trans-setting to other orders of the adding mechanism the said connections with the multiple stroke mechanism; whereby division may be performed without manual resetting of the divisor.

54. In a multiple-order calculating machine, in combination: denominational series 50 of keys, multiple order adding mechanism adapted to be driven by said keys for the setting of the adding mechanism to represent a dividend, multiple stroke mechanism 55 having connections with the adding mechanism whereby the dividend may be diminished by repeated additions of the complement of a division, means for actuating the 60 said multiple stroke mechanism, and devices whereby the actuating means automatically causes the said connections to be trans-set to other orders of the adding mechanism, for the deriving of the successive quotient figures.

55. In a multiple-order calculating machine, in combination: denominational series of keys; multiple order adding mechanism adapted to be driven by said keys for the setting of the adding mechanism to represent a 70 dividend; multiple stroke mechanism having connections with the adding mechanism whereby the dividend may be diminished by repeated additions of the complement of the divisor; automatic control mechanism having orders and indicators on which may be set a number inclusive of the quotient, the 75 said control mechanism being adapted to automatically trans-set said connections after a certain number of operations of the 80 multiple stroke mechanism; means for actuating the multiple stroke mechanism and the control mechanism; and means for resetting any order of the control mechanism, when the remainder will no longer contain the divisor, 85 so that the order so reset will cause no further stroke of the multiple stroke mechanism.

56. In a multiple-order calculating machine for performing division by complementary addition, in combination: multiple order adding mechanism; means for setting the orders of the adding mechanism to represent a dividend; multiple stroke mechanism having connections with the adding 90 mechanism whereby the dividend may be diminished by repeated additions of the complement of the divisor; automatic control mechanism having orders and indicators 95 on which may be set a number inclusive of the quotient, the said control mechanism being adapted to automatically trans-set said connections after a certain number of operations of the multiple stroke mechanism; means for actuating the multiple stroke 100 mechanism and the control mechanism; and means for resetting any order of the control mechanism, when the remainder will no longer contain the divisor, so that the order 105 so reset will cause no further stroke of the multiple stroke mechanism.

57. In a unitary multiple order calculating machine, in combination: adding mechanism; a supporting frame for the same; a supplemental frame hinged thereto; and automatic multiplying mechanism mounted on the said supplemental frame and removable from and restorable to operative relation with the said adding mechanism by the hinging movement of the supplemental 110 frame.

58. In a calculating machine: the combination of accumulator mechanism and actuating mechanism therefor to give positive and negative results to the reading of said 115 accumulation, said actuating mechanism having two independent manipulative means each adapted to drive it.

59. In an automatic calculating machine in combination; a multiple order series of 120

- key setting-devices for the setting of one factor, and another multiple order series of key setting-devices for the setting of another factor, a device for actuating the machine whereby the setting devices control the actuations to give the calculative result of the two factors, and locking means to prevent actuation until both factors have been set.
10. 60. In a multiple order unitary calculating machine the combination of a multiple series of key driving means of manipulation; a single unit device serving as another means for actuation, and devices such that when one means of actuation is set for use the other is locked against use.
15. 61. In a unitary automatic calculating machine, the combination of two separate sets of multiple order key setting devices for setting the two factors of a calculation, a device for actuating the machine to give the result of the two factors, and a device for actuating which transposes one of the multiple order key setting devices into a key driven means by the manipulation of which calculation may be performed independent of other means.
20. 62. In an automatic calculating machine; the combination of two multiple order factor setting devices; one of which is used to set the constant factor and the other to set the controlling factor, the controlling factor setting devices having the capacity for the setting of ciphers that may appear in the factor to be used and the capacity of controlling in accordance with said ciphers.
25. 63. In an automatic calculating machine; the combination of two multiple order factor setting devices; one of which is used to set the constant factor and the other of which is used to set the controlling factor, the capacity of both when set giving a product greater than the accumulative reading capacity of the machine; and means by which the constant factor setting is trans-directed from left to right by the setting of the controlling factor, so that the product of the higher places in the constant factor may be conserved within the reading capacity of the machine.
30. 64. In an automatic calculating machine; the combination of two multiple order factor setting devices, one of which is used to set the constant factor and the other of which is used to set the controlling factor; and means whereby each order of the controlling factor may be zeroized, independent of the other orders, during calculation, for purpose of calculating with an unknown controlling factor.
35. 65. In an automatic calculating machine; the combination of two multiple order factor setting devices, one of which is used to set the constant factor and the other to set the controlling factor, and a series of indicating devices connected with the controlling factor devices, which indicate the factor set; said indicator devices diminishing their indication in accord with the action of the controlling factor upon the constant factor, during the process of calculation.
40. 66. In an automatic calculating machine the combination of multiple order setting devices for setting the constant factor and other multiple order setting devices for setting the controlling factor and a device which by the single action clears or neutralizes a constant factor setting device so that it may be reset.
45. 67. In an automatic calculating machine; accumulator mechanism, actuating mechanism therefor, constant factor setting devices which control the digital actuations of said actuating mechanism and a one motion device which zeroizes the accumulator mechanism and also clears the constant factor setting device when desired.
50. 68. In a unitary calculating machine, the combination of an accumulator mechanism, ordinal rows of digital keys and means by which said keys may operate the accumulator mechanism; a device independent of said keys for actuating the accumulator mechanism, and other rows of digital keys which control the actuations of said device.
55. 69. In a calculating machine, accumulator mechanism, actuating mechanism, setting devices which control the digital, ordinal and multiple actuations of said actuating mechanism, and devices which automatically clear and neutralize the said setting devices severally and together.
60. 70. In an automatic calculating machine, the combination of accumulator mechanism, actuating mechanism, and factor setting mechanism co-operating in automatic calculation; a zeroizing mechanism for the accumulator mechanism; and locking mechanism whereby said zeroizing mechanism is positively locked against action during automatic calculation.
65. 71. In an automatic calculating machine a series of numeral wheels forming parts of the accumulator, and another series of numeral wheels serving as predetermined indicators of the multiple and ordinal degrees of calculation.
70. 72. In an automatic calculating machine, two series of mechanically connectible numeral wheels, on which are expressible respectively two predetermined factors of an example, and automatic means co-operating with and effecting connection between said two series of wheels and causing the result of the calculation to be shown on the wheels of one of said series.
75. 73. In an automatic calculating machine, two series of mechanically connectible nu-

meral wheels, on which are expressible respectively two factors of an example, and means, coöperatively effecting connection between said series of wheels whereby the reading of one series of said wheels is caused to diminish and the reading of the other series of said wheels is caused to be augmented, in the performance of an example, the diminishing factor series of wheels serving as an indicator of the extent to which the performance of the example has proceeded and the other series of wheels serving as a register.

74. In a calculating machine, having means by which a constant may be repeated in ordinal degrees either positively or negatively, a series of setting members having inter-operative connection and which control the repetition of the constant and which by their inter-operative connection cause the control of the repetition in the various orders to coincide with the setting of said members.

75. In an automatic multiple stroke calculating machine, in combination: adding mechanism, multiple stroke mechanism connected with the adding mechanism, and multiple control mechanism which automatically determines the number of strokes of the multiple stroke mechanism, the multiple control mechanism being adapted to be reset at will during the performance of an example.

76. The combination of a multiple order key-driven adding mechanism, a multiple stroke mechanism, means for connecting the multiple stroke mechanism with the adding mechanism, and multiple stroke control mechanism, in successive orders arranged to automatically determine the number of strokes made by the multiple stroke mechanism, said multiple stroke control mechanism having means whereby one order of said control mechanism, upon the completion of its operation, causes a succeeding order to begin operation.

77. In a calculating machine, multiple control mechanism arranged in successive orders, and comprising means whereby one order of said control mechanism, upon the completion of its operation, automatically causes a succeeding order to begin operation.

78. In a multiple stroke calculating machine, stroke control mechanism arranged in successive orders, and cipher control mechanism arranged to prevent accumulation while the stroke control mechanism continues in operation.

79. The combination of a multiple order key-driven adding mechanism, a multiple stroke mechanism, means for connecting the multiple stroke mechanism with the adding mechanism, and locking means preventing the disconnection of the said mechanisms until the completion of an example.

80. A key set crank operated machine having capacity for multiple order calculation, and having in combination with it mechanism by which calculation may be accomplished by the mere depression of the keys without the operation of the crank mechanism.

81. In a calculating machine, in combination with key-driven adding mechanism comprising multiple order accumulator mechanism, and digitally actuating column actuators for driving the same: automatic multiple stroke mechanism and means for connecting the same with the said column actuators and causing the adding mechanism to be key-set; substantially as specified.

82. In a unitary calculating machine, the combination of multiple order accumulator mechanism: multiple order inter-operative actuating mechanism therefor; and a single element operating device which by its action gives automatically varying multiples of additive movement to the said actuating mechanism and accumulator mechanism.

83. In a calculating machine having inter-operative additive orders, the combination with said orders, of means for setting said orders, and for automatically trans-setting, for the purpose of automatic multiple calculation.

84. In a calculating machine, the combination of accumulating mechanism, multiplying mechanism connected therewith, means for trans-setting the connections between the multiplying mechanism and the accumulating mechanism, and automatic means for causing such trans-setting to be continued past a cipher in one of the factors and for preventing the actuation of the accumulating mechanism for such cipher.

85. The combination, in a unitary calculating-machine, of key-driven adding-mechanism, key-set multiplying-mechanism, and means irrespective of the keys for driving the said multiplying-mechanism.

86. The combination, in a unitary calculating-machine, of key-driven adding-mechanism, and key-set multiple-stroke mechanism coöperatively connectible with the adding mechanism.

87. The combination, in a unitary calculating-machine, of key-driven calculating-mechanism, and key-set calculating-mechanism coöperatively connectible with the key-driven mechanism.

88. In a calculating machine, in combination: ordinal series of digital keys for finger manipulation in key-driven actuation; and the mechanism so driven by said keys; and converting devices connected with said mechanism whereby said keys become mere setting devices to determine a factor-setting.

89. In an automatic calculating machine,

- in combination: digital factor-setting devices; a main driving device; and a stop device acting to stop said driving device, such action being effected by the factor-setting devices, to stop the operation of the machine at the end of a calculation. 70
90. In a calculating machine, the combination of constant-factor setting-devices having co-digital markings, and controlling factor-setting devices, the combined setting of which control additive actuation in negative complementary calculation. 75
91. In a calculating machine adapted for performing division by the repeated addition of the complement of the divisor, in combination: an accumulator mechanism; multiple actuating devices for said accumulator mechanism; digital setting devices for said multiple actuating devices, having two related markings by one of which the complement of the divisor may be set in terms of the divisor; and means whereby the actuations of the said multiple actuating devices are caused to affect successively different orders of the accumulator mechanism. 80
92. In a calculating machine adapted for performing division by repeated addition of the complement of the divisor, in combination: adding mechanism; digital setting devices for said adding mechanism, having two related markings, by one of which the complement of the divisor may be set in the terms of the divisor; multiple actuating devices for said adding mechanism, which are affected by the said digital setting devices so that the setting of the adding mechanism gives a like setting of the said multiple actuating devices; and trans-setting devices which automatically trans-set the digital setting of the said multiple actuating devices. 85
93. In a calculating machine, multiple ordinal control mechanism, each order of which may be adapted for the control of the machine, and one order of which controls another order. 90
94. In a calculating machine, rotatable multiple ordinal control mechanism, each order of which may be adapted for the control of the machine, and one order of which controls another order. 95
95. In a calculating machine, in combination: ordinal series of digital keys for finger manipulation in key driven actuation; and the mechanism so driven by said keys; and means connected with said mechanism whereby said keys become mere setting devices to determine a factor setting. 100
96. In a unitary automatic calculating machine, the combination of a key-driven calculating machine and a multiplying mechanism connectibly and automatically operative for positive and negative calculation. 105
97. In a calculating machine, in combination: digit-control mechanism arranged in successive orders; and cipher-control mechanism arranged to prevent accumulation while the control mechanism continues in operation. 110
98. In an automatic calculating machine for performing multiplication, in combination: accumulating mechanism; means for setting the same to represent a factor; rotary control mechanism; means for setting the same to represent the other factor; means for actuating said mechanisms; and co-operative numeral devices for showing the product of said factors. 115
99. In a calculating machine, in combination: numeral wheels for digital setting and digital accumulation; actuating mechanism therefor having the capacity of being key-set or key-driven; the keys for said mechanism, and a clearing-device operating at one movement to clear the said key-setting and either the numeral-wheel setting or the accumulation that may have been effected. 120
100. In an automatic calculating-machine, the combination of a factor-cipher controlling device, and a factor-setting device controlling the said cipher-controlling device in positive and negative calculation. 125
101. In an automatic calculating-machine the combination of mechanism capable of being set for automatic calculation, and locking-devices controlling operation and requiring the setting of factors sufficient to effect calculation before the locking action is released. 130
102. In an automatic calculating machine, the combination of mechanism capable of being set for the factors of and effecting automatic calculation, and devices which during calculation clear said setting. 135
103. In a calculating-machine, in combination: two key-boards, each of multiple-order series of keys and respectively determining the factors of calculation; accumulator-mechanism; actuating-mechanism for automatically effecting calculation in accordance with the factors determined by the keys of the respective keyboards; and driving mechanism; said keyboards and accumulator-mechanism and actuating-mechanism each having over six mutually identical ordinal groups of mechanism, whereby the structure is adapted to be ordinarily extended to great capacity. 140
104. In a calculating-machine, in combination: accumulator mechanism; ordinally disposed actuators therefor; means for setting the actuators to predetermine a factor; and means for automatically transsetting the aforesaid setting of the actuators, for different ordinal places of another predetermined factor, without intervening key manipulation; substantially as specified. 145
105. In a calculating machine, the combination of orders of accumulating mecha- 150

- nism, orders of multiplying mechanism adapted to give movements to orders of said accumulating mechanism selected at will, means for connecting at will certain 5 of said orders of multiplying mechanism with certain of said orders of accumulating mechanism, and means for automatically regulating the number of movements of the connected orders of multiplying mechanism 10 by a predetermined setting of a plurality of the orders thereof to actuate the connected orders of accumulating mechanism for successive numbers of times, without intervention of the operator, according to the values of 15 the successive digits of the multiplier.
106. In a calculating machine, the combination of, orders of accumulating mechanism each having an order of keys and a lever; orders of multiplying mechanism 20 adapted to give movements to orders of said accumulating mechanism selected at will, means for connecting at will certain of said orders of multiplying mechanism with certain of said levers of the accumulating 25 mechanism, and means for automatically regulating the number of movements of the connected orders of multiplying mechanism by a predetermined setting of a plurality of the orders thereof to actuate the connected 30 orders of accumulating mechanism for successive numbers of times, without intervention of the operator, according to the values of the successive digits of the multiplier.
107. In a calculating machine, the combination of orders of accumulating means, 35 corresponding orders of multiplying mechanism each of which is adapted to give a predetermined number of movements to its corresponding order of accumulating means, means for setting orders of said multiplying mechanism for predetermined successive numbers of actuating movements, and automatic means whereby a succeeding order of said multiplying mechanism is set 40 for a predetermined number of movements corresponding with the setting of the preceding order.
108. In a calculating machine, the combination of orders of accumulating means, 50 corresponding orders of multiplying mechanism each order comprising an actuating lever, means for connecting each lever with the actuating element of its corresponding order of accumulating means, means for setting said levers for predetermined distances of movement, actuating means for moving said levers which have been set and for giving to each lever its distance of movement according to its setting, and automatic 55 means for regulating the number of movements of each lever.
109. In a calculating machine, the combination of orders of accumulating mechanism, orders of multiplying mechanism 60 adapted to give movements to orders of said 65 accumulating mechanism selected at will, means comprising pairs of connectible and disconnectible levers for connecting at will certain of said orders of multiplying mechanism with certain of said orders of accumulating mechanism, and means for automatically regulating the number of movements of the connected orders of multiplying mechanism by a predetermined setting of a plurality of the orders thereof to actuate the connected orders of accumulating mechanism for successive numbers of times, without intervention of the operator, according to the values of the successive digits of the multiplier. 70
110. In a calculating machine, the combination of orders of accumulating mechanism, orders of multiplying mechanism one for each order of accumulating mechanism, means for separably connecting said orders 85 respectively according to the digits and places of the multiplier, whereby orders of the multiplying mechanism may operate corresponding connected orders of accumulating mechanism, means for operating the connected orders of multiplying mechanism, automatic controlling means whereby the connected orders of multiplying mechanism are caused to operate with predetermined successive numbers of accumulating movements according to the digits of the multiplier, and automatic means for releasing the connection between an order of accumulating mechanism and an order of multiplying mechanism and causing the connection of 90 others of said orders at times between said successive numbers of accumulating movements, according to the places of the multiplier. 95
111. In a calculating machine, the combination of orders of accumulating means, corresponding orders of multiplying mechanism each order having an actuating element for an order of said accumulating means, means for connecting said actuating 100 elements of the multiplying mechanism with the corresponding actuated elements of the accumulating mechanism respectively, means for setting said actuating elements for predetermined distances of movement respectively, actuating means for moving the set actuating elements each for its predetermined distance of movement according to its setting, and automatic means for regulating the number of movements of each of said 105 set actuating elements. 110
112. In a calculating machine; the combination of mechanism adapted to give digital values in multiple forms of calculation, and a single device acting to control the aforesaid mechanism in two orders alternately during multiple forms of calculation performed in a multiplicity of orders without further setting of multiplier factors. 115
113. In a calculating machine, in combi- 120
- 130

nation: manipulative means for setting up simultaneously a multiple-place multiplicand and a multiple-place multiplier; and automatic multiplying mechanism effecting 5 the completed multiplication with devices that throughout the operation remain and operate in fixed ordinal places in the machine.

114. A calculating-machine that automatically performs multiplication in which both 10 factors are multiple-place and completely pre-determined, and effects the entire operation with mechanism whose ordinal positions are permanent, said mechanism remaining 15 and operating in fixed ordinal places in the machine.

115. In a calculating machine, the combination of accumulating means, multiplying means, and multiple-control devices for regulating the numbers of operations of said multiplying means and arranged in orders, 20 said multiple control devices having automatic means whereby the desired number of said operations is caused successively in each of said orders according to the digits 25 and places thereof of the multiplier.

In testimony whereof I affix my signature in presence of two witnesses.

JOSEPH A. V. TURCK.
